UNITED STATES PATENT OFFICE.

DAVID S. HULFISH, OF TORONTO, ONTARIO, CANADA, ASSIGNOR TO CANADIAN INDEPENDENT TELEPHONE COMPANY, LIMITED, OF TORONTO, ONTARIO, CANADA, A CORPORATION OF CANADA.

TELEPHONY.

1,218,182.

Specification of Letters Patent.

Patented Mar. 6, 1917.

Application filed May 13, 1912, Serial No. 696,902. Renewed August 7, 1915. Serial No. 44,292.

To all whom it may concern:

Be it known that I, DAVID S. HULFISH, engineer, a citizen of the United States of America, residing at Toronto, in the county 5 of York and Province of Ontario, Canada, have invented certain new and useful Improvements in Telephony, of which the following is a specification and a description of the manner and process of constructing 10 and using the same, intended to be in such full, clear, concise, and exact terms as to enable any person skilled in the art to make and use the same.

My invention relates to telephone systems 15 in general and to the application of methods and apparatus for telephone switching in central offices of telephone exchanges. In some of its details, it is particularly adapted to systems of the "Lorimer" type of automatic telephone devices and I have shown it in this application, applied specifically to a system of circuits for the "Lorimer" type of automatic apparatus with suggestions from time to time as to the general application 25 of certain features of my invention to the general art of telephony in central offices whether automatic or manual.

My invention has for its objects the following:

(A) An improved system for indicating 30 electrically the numbers for identifying a calling line, being a decimal indicator composed of a bank of relays.

(B) A method of calling among lines entering 35 an automatic telephone exchange whereby the order of answering contemporaneously existing calls may be varied from time to time.

(C) A combined sequence switch and 40 vision starter.

(D) A system of test circuits for determining 45 the busy or idle condition of a tested circuit, whereby the tested circuit may have either of two potentials impressed upon it during its busy condition and the testing circuits will reject it if it bears either potential.

(E) An improved off-normal device in combination with a switch having two 50 movements of selection such that the off-normal device will show an off-normal condition when the associated automatic switch is off-normal in either of its movements of selection, the automatic switch being free

to move in either movement from its position of rest. 55

(F) An improved system for testing a telephone line for busy or idle condition, and the subsequent adjustment of automatic switches in accordance with the result of 60 the test, including a locking relay for recording the result of the transient test, the relay being held locked for a sufficient time for reliable operation of the automatic switches requiring control subsequent to the 65 test and dependently upon the test.

(G) An improved system of commutators and associated circuits for ringing code 70 ringing upon party lines in an automatic telephone exchange.

(H) An improved system of controlling 75 circuits for an automatic telephone connective apparatus, controlled by the two telephones of the connection, and controlling the release of the connection at the will of either 80 of the telephone users.

(K) A system of lamp signals for an 85 automatic telephone exchange in which a different order of signals is produced when the line called for is busy as compared with the signals produced when the line called 90 for is tested and found idle; also, an improved signal in a set of lamps whereby two lamps each having a definite meaning when burning alone, may be caused to burn simultaneously to express a third and independent meaning. 95

(M) An improved timer device or slow relay.

(N) An improved timer device having 90 alarm points and automatic release points and adapted to close the alarm points first and to close the automatic release points after a delay subsequent to the closing of the alarm points whereby an abnormal action 95 is at first indicated by an alarm and later is relieved automatically and the apparatus restored.

(P) An improved circuit and means in connection with an automatic lamp alarm 100 and release device whereby the attendant in charge of an automatic exchange may disable either the automatic release functions of the telephone office or the lamp alarm functions of the telephone office, but 105 not both.

(Q) An improved multiple brush for an automatic switch, engaging a plurality of

- contact points on the same level and closing through them a plurality of simultaneous circuits.
- (R) A brush arrangement by which two independent multiple brushes act upon the same level of contact points and close simultaneous and independent circuits through the same level of points, each circuit being closed twice in a single cycle of the switch, one closure for each multiple brush.
- (SA) A system of mutual circuits between two automatic switches, such that the return of either to normal will return the other to normal also.
- (SB) A system of main circuits and of auxiliary circuits in an automatic exchange, such that the control of an automatic switch normally by a line and its telephone is substituted by a central office auxiliary circuit in case the switch has no connected line.
- (SC) A system of circuits by which the pilot switch when at normal restores other switches to normal, namely, the primary connector and the signal controller.
- (SD) A system of driving devices and circuits for a timing device whereby one timer may be driven at different speeds at different times.
- (SE) I provide a division starter with a timing device whereby a second division will be started in case the first does not respond promptly.
- (SF) A novel disabling circuit for a division starter when all divisions are busy.
- (SG) A method of using duplicated devices or electrical circuits having a common destination by using them in order of rotation.
- (SH) A method of using a group of electrical circuits having a common destination by dividing them into two small groups, one small group used in rotation and the remaining small group used as an overflow group and used in numerical order of precedence.
- (SK) A system of circuits and apparatus for applying to the general practice of telephony the principles of selection of duplicated circuits last mentioned above.
- (SM) A system and method of metering calls in which a call is recorded upon the meter of the calling line only as a result of the response of the called line.
- (SN) A detail of metering system for general application in telephone exchanges by which certain lines may be designated as "free service" lines and calls terminating upon these lines will not register upon the meter of the calling line when the "free service" line responds.
- (SP) The system for seizing a busy line with disregard of the guarding condition.
- (SQ) An improved telephone for a subscriber's station suitable for a party line having features of reverting call ringing.
- (SR) An improved party line telephone with an interference device.
- In the drawings which accompany and form a part of this specification
- Figure 1 shows the circuits of the primary connector or A-line switch.
- Fig. 2 shows the circuits of the pilot switch and thousands or ringing register.
- Fig. 3 shows the circuits of the relays, commutators, division timer and sundry other apparatus.
- Fig. 4 shows the circuits of the signal controller.
- Fig. 5 shows the circuits of the interconnector or trunk selector.
- Fig. 6 shows the circuits of the secondary connector, or B-line switch.
- Fig. 7 shows the circuits of the line relays constituting the decimal indicator.
- Fig. 8 shows the circuits of the decimal register controller.
- Fig. 9 shows the circuits of the division starter which is also the permutation controller for the line relays or decimal indicator.
- Fig. 10 shows the circuits of a telephone for a line having but one telephone.
- Fig. 11 shows a simplified diagram of the circuits for conversation and for release under subscriber's control.
- Fig. 12 shows the circuits of the rotational busy test.
- Figs. 13, 14 and 15 show details of "free meter lines."
- Fig. 16 shows the circuits of a telephone for a party line.
- Fig. 17 shows a party line telephone having interference features for party-line.
- In the figures, numerals smaller than 100 although sometimes used for identification, are not strictly reference labels within the ordinary meaning of the term; they are numerals indicating the order or relation of the parts adjacent to which they are found, or to which they directly pertain, as indicating the order of contact points in a row, or the order of rows in a contact bank; for example, the numerals 1-to-44 in Fig. 2 are stamped upon the apparatus as built and used and form a part of the apparatus illustrated by the drawing. Reference numerals 101 to 199 have been reserved for conductors, entering the pilot switch, 200 to 399 for apparatus parts, and 400 and higher for miscellaneous conductors. Like numerals refer to like parts throughout the many figures.

The switches.

The switches are of three types, called the cylinder type, the register type, and the commutator type.

A switch of the cylinder type is illustrated in Fig. 4. The horizontal rows of

small circles represent the fixed contact points projecting from the developed inner surface of an annular casting of insulating material; upon these contact points there move horizontally from left to right a set of brushes, shown in the figure as small flat parallelograms resting upon the points of the first vertical set of points. A controlling magnet or clutch magnet 213 has an armature adapted to engage a notched disk to restrain the disk from turning. The disk is attached to the brushes of the cylinder switch. When the clutch magnet is charged by current passing through it, its armature 5 is withdrawn from the notched disk and the disk is permitted or caused to revolve in the direction shown by the arrow, carrying with it the brushes of the associated cylinder. The disk (and therefore the brushes of the switch) may stop only in positions corresponding to notches in the periphery of the disk, and these notches therefore represent the only possible stop positions of the brushes of the switch.

25 In the primary connector of Fig. 1, the stop positions of the brushes are all but one in the first quadrant of revolution, as indicated by the location of eleven notches in the clutch disk.

30 In the pilot switch of Fig. 2 there are fourteen stop positions, irregularly distributed. The vertical sets of contacts of the cylinder are numbered horizontally 1-to-44, the stop positions of the brushes are numbered in the line above, 1-to-14, each number appearing twice, over each of the two adjacent sets of points occupied by the main set of pilot brushes in each of the indicated stop positions, resting normally when not 35 in use upon No. 1 stop position, or contact sets 1 and 2. The horizontal rows of cylinder points are numbered 1-to-14 from top to bottom, at the left.

40 The pilot switch of Fig. 2 has also a set of auxiliary brushes, their pairs on 3rd, 7th and 9th levels, resting normally on points of 34th and 35th sets and moving with the main brushes. The main brushes of the 7th level are connected by a wire to the auxiliary brushes of the same level.

45 In the signal transmitter controller of Fig. 4, the clutch disk has four notches. The disk is geared to the brushes in the ratio of one revolution of the disk for two revolutions of the brushes. The complete cycle of 50 operations of the switch is effected in two complete revolutions of the brushes, or one revolution of the disk. The stop positions of the brushes are: normal position on contact set No. 1, first stop position on contact set No. 43 just before the end of the first revolution; second stop position on contact set No. 1; third stop position on contact set No. 43 just before the end of the second revolution.

The interconnector of Fig. 5 and the secondary connector of Fig. 6 are switches similar to that of Fig. 1. The division starter of Fig. 9 is a switch similar to that of Fig. 2 but with a different distribution of stop notches, without a register, and with a single set of brushes.

In this specification, a contact point in a cylinder switch (or in a register bank) is identified by giving its vertical row counting from the left and its position in the row counting from the top; thus: 1X1, upper left point of any bank; pilot 23X14, the pilot point, middle of bottom row of bank connected to conductor 105. When two 50 points are engaged by two connected brushes, the points are indicated by a hyphen connection; thus, pilot points 1X13-12, where the points are in the same vertical row, or pilot points 27X3-28X3, pilot points 39-7X7-7, 55 where the engaged points are not in the same vertical row.

A switch of the register type is illustrated in Fig. 1 at the top. The arcs of small circles represent rows of fixed contact points, upon which move the brushes shown as small rectangles upon set No. 0 of the points. The brushes are carried by the ratchet, which is under spring tension against the pallet, and which is permitted to move step-by-step under control of the register magnet 214. This register, complete, is carried by the mechanism carrying the cylinder brushes, to which the register parts are wired. It is restored to normal position, after having been operated, by mechanical devices which restore it during the second quadrant of revolution of the clutch disk.

The ringing register of Fig. 2 is in fixed position, but is located adjacent to an associated cylinder switch, and is restored to normal by the return of the adjacent cylinder switch, such as the pilot switch of Fig. 2. The brushes of the register are reversed, moving from right to left.

The registers of Figs. 5 and 6 are similar to that of Fig. 1 and are similarly restored.

A switch of the commutator type is illustrated in Fig. 8, the decimal register controller. The developed commutator ring of 115 long segment 232 and fifty smaller segments, with its associated brushes, conductors, relay and clutch, form the decimal register controller as a whole, whose function it is to operate the decimal register of a started division to assist in the identification and seizure of the calling line.

120 There is one decimal register controller for each switchboard section or group of divisions, one such controller thus serving all 125 of a group of lines and controlling the decimal registers of all of the corresponding group of connective divisions.

The decimal register controller brushes are equipped with the direct-clutch, which 130

starts its associated brushes when the clutch magnet is charged and stops them when the clutch magnet is discharged and the dog of the clutch drops into the next notch of the clutch disk. The disk has four notches, but as the two brushes are duplicates and the switch accomplishes its electrical cycle in one-half revolution, there result from the four notches but two stop positions with one brush upon the forty-sixth small segment, 230, and with the brush upon the fiftieth or last small segment, 231, the companion brush in each instance being upon the long segment, 232.

The switch of Fig. 9 is the division starter and line sequence controller. The pilot clutch magnets of the connective divisions when normal are charged only through this starter. The clutch magnet of the first connective division is shown at 215 in Fig. 2, being connected to wire 121 which is shown attached to cylinder point 3X6 in Fig. 9; the corresponding wire of a second division is shown attached to cylinder point 7X6 in Fig. 9. The division of Fig. 2 is further associated with Fig. 9 by the wire 128 shown attached to cylinder point 3X3 in Fig. 9; the corresponding wire of a second division is shown attached to cylinder point 7X3 in Fig. 9. These two wires, upon cylinder points 7X6 and 7X3 in Fig. 9 are illustrative of a second complete division such as shown in Figs. 1, 2, 4, 5, 6 and parts of Fig. 3. The starter is sole per group of divisions (say six to twelve) and per associated group of lines (say one hundred).

The single-line telephone.

The automatic substation telephone comprises the usual items of a telephone set, and in addition an automatic call sender. The circuits for a single-station-line telephone are shown in Fig. 10.

Grounded brushes, 240, of which four are shown, are adjustable by moving projecting buttons by the telephone user according to indicators to place ground upon one pin in each segment (about a quadrant, as drawn) of a circle of pins 241, which contains several such segments and upon which a conducting arm 242, rides.

The means for propelling the arm 242 over its circle of pins comprises a main spring, a crank for winding the main spring, and an electric escapement controlled by the magnet 248. The escapement permits the arm to move in steps, forty-three steps being required to complete one revolution. The electric escapement is ineffective to make the first step, the first step being made mechanically, preferably by the crank which winds up the main spring, the electric escapement then being effective when properly controlled to make the remaining forty-two steps.

The devices of the central office are adapted to send forty-two impulses for the control of the call sender escapement, forty-one from the signal controller and one from communicator No. 8.

70

To set the signal transmitter to effect connection with a desired telephone substation, the indicator buttons are set to the directory number of that substation by moving the buttons independently to positions in which they will indicate the said directory number. The wires from the first two indicator points of each set to the contact pins in the circle engaged by the arm 242 are shown in the diagram, Fig. 10. The remaining points are connected in corresponding manner, except the last or tenth point, (directory number "9,") which is left unconnected. Contact arm 242 normally engages the point 243 and thus normally holds the talking bridge subject to control by the hook switch 246. Connection from the first conductor of the line 421, to the arm 242 is made through a brush connection. When the arm 242 is moved forward mechanically one step by the operation of starting a call, it engages a contact pin 244 which is connected directly to earth or through a return wire to minus battery.

80

A switch, 247, composed of a pair of contact springs, is adapted, when closed, to complete the circuit for the stepping magnet 248 from the second conductor of the line 422, to earth. The springs of the switch 247 normally are disengaged from each other but are forced into engagement by means of a cam lever 249 moved by a cam disk 239 secured to the shaft of the contact arm 242.

95

A notch in the cam disk 239 permits the springs of the switch 247 to move the arm 249 and to disengage themselves when the arm 242 stands in the normal position, or in connection with pin 243. When the arm 242 is moved from its normal position, by the action of starting the call, the cam disk 239 operates the lever 249 to close the switch 247, the disk 239 then preserving the closed condition of the switch 247 until the arm 242 completes its revolution and resumes its engagement with the pin 243.

105

The lines entering a central office are divided into groups of, say, one hundred lines per group, and the automatic equipment of the central office is for the most part divided also, each group of apparatus serving a group of telephone lines; such a group of apparatus is called a switchboard section, or simply, a "section".

110

In each such section the switches for the most part are grouped into groups called connective divisions, each group or division constituting a connective unit analogous to a switching cord pair equipment in a manual telephone switchboard,

125

The automatic switches which make up a connective unit or connective division in the figures of this application are: primary connector or A-line switch, Fig. 1; pilot switch and thousands or ringing register, Fig. 2; (relays, timer, lamps, condensers, resistances, Fig. 3;) signal controller, Fig. 4; interconnector, Fig. 5; secondary connector or B-line switch, Fig. 6.

10 The automatic switches of a section, common to all divisions, are—decimal register controller, Fig. 8; division starter, Fig. 9.

The total process of connecting two lines automatically in such an office comprises:

15 (1) A primary adjustment by which a connective division is associated with a calling line. (2) Selective adjustments by which circuit-selecting switches are adjusted to select such circuits as will result ultimately

20 in associating the connective division with the line desired by the calling line and indicated by the preliminary manual adjustment of its call sender. (3) Test and preliminary ring by which the line selected is

25 rung upon if not found engaged. (4) Repeated ring until the call is answered. (5) Maintenance of a condition for conversation after the ring is answered and release by subscriber's control. (6) Restoration au-

30 tomatically of all parts of the connective division after conversation and release. (7) Throughout all of these operations the connective division is supervised by a system of lamp signals which operate to announce

35 normal action and abnormal action, if any.

(8) The division is further guarded by automatically operative restoring or normalizing circuits and devices which act to restore it to normal condition for further

40 service in event of an abnormal operation. (9) Special service requirements compel some specialization of apparatus or circuits, or both.

(A) Early forms of decimal indicators, 45 constructed for one hundred lines, have comprised a rotating device capable of being stopped in one hundred different positions, each position corresponding to a line served by the device. When thus stopped by a call-

50 ing line, the decimal indicator identified the calling line by placing an electrical potential upon two identified and line-identifying wires in two sets, each set comprising ten wires and one wire being identified in

55 each set. These sets were the decimal set and the unit set. By the wire identified in the decimal set, the tens digit of the calling line was made known and by the wire identified in the units set, the units digit of the calling

60 line was made known. My improved decimal indicator comprises one hundred line signal or line-indicating relays, each relay

65 having two pairs of contact points, one pair being connected properly to place an identi-

wire in the tens set corresponding to the line of that relay and the other pair of contact points being similarly connected to place an identifying potential upon the proper wire in the units set. The charging of the 70 line relay thus identifies the calling line by identifying two conductors which in turn identify the line, the subsequent selection of the line being accomplished by the division

upon fundamental principles heretofore 75 used. Associated with each line signal re-

lay is a line cut-off relay and associated with each units wire is an additional signal re-

lay, making a bank of two hundred ten re-

lays in all required for a completely equipped 80 decimal indicator for one hundred lines.

My improved relay decimal indicator offers instantaneous response to a calling line, thus eliminating the period of time required for the rotating device to engage the calling line 85 and my improved relay device obviates certain adjustments which were involved in the rotating device.

(B) In the rotating decimal indicator the calling lines were served on either of two 90 principles of selection, dependent upon the circuits used. The first principle was that

the lines should be served in rotation as they might call, the search being made in numerical order and each calling line being 95 assigned to a connective division before the

rotating decimal indicator proceeded further in its search, the rotating device being held motionless upon a calling line so long as all connective divisions were engaged. 100

The second plan was that lines should be served as in the first plan until all connective divisions became engaged, after which the rotating device would not stop upon any

calling line unless a connective division were 105 idle and in condition to serve the line. The

second plan therefore left to a matter of chance the selection of one calling line from several calling lines, when, all connective 110

divisions having been busy, one connective division was released and made available for serving one of the several calling lines. In

my improved decimal indicator, the lines are arranged in a series circuit in an order 115

whereby certain lines have precedence over all others and are served in precedence when the connective divisions are insufficient to serve all calling lines. To provide against

immoderate use of the connective divisions by certain favored lines to the exclusion of 120

lines less favorably located upon the series circuit, I provide a permutation device which from time to time changes the order 125

of precedence of the lines and thereby distributes the service of a group of connective divisions more uniformly among the lines

served by that group.

(C) I accomplish the permuting requirements of my improved decimal indicator by utilizing the cylinder switch of the division 130

starter and in the drawings which accompany this specification, I show the lowest six levels of the division starter cylinder thus utilized.

(D) The full economy of a trunk circuit, having a minimum number of conductors, in an automatic telephone exchange, can be realized at times only by using some one conductor for more than one function in the progress of setting up, maintaining and disrupting a connection. I have met a requirement of this nature by using the same conductor for the operation of the clutch of a distant switch and for a busy test conductor offering a condition suitable for electrical test, to determine whether a distant switch is in normal position or otherwise. As the conductor thus used will vary its potential from time to time as operating currents do or do not pass over it to control the distant switch, it is necessary for the testing circuit at any moment to show that the distant switch is engaged, regardless of the variations of potential upon the conductor serving the double purpose of switch control and busy test. I have provided three different potentials in the automatic central office of which two may be applied to the conductor in question for such switch control, the third being applied for test purposes, the test-and-control conductor being so associated with apparatus that it will be entirely open only when the distant switch is idle so that no current will flow from the testing devices to the wire in question if the switch be idle but current will flow from the test devices to either of the two operating potentials if the switch be busy. By the flow of current from the test device, it may be known that the distant switch is busy and the test device may be controlled in accordance therewith.

(F) In the automatic telephone system shown in the accompanying drawings it is necessary to adjust the selecting switches to variant positions according as the selected line is found to test engaged or free. If the tested line be found engaged, the pilot switch is advanced immediately after the test but if the tested line be found free, the signal controller is advanced immediately after the test and the pilot switch is advanced subsequently.

To provide ample time for moving these switches to their positions of adjustment in accordance with the result of the test upon the selected line, I provide a locking test relay which by locking will record the result of the test indefinitely or for such a length of time as may be required for the adjustment of the selective switches involved.

To insure the maintenance of the locking circuit for a sufficient time to move the pilot switch, I carry the locking circuit through the pilot switch, and the locked relay.

(G) In my improved system of commu-

tators for ringing in code manner upon party lines, I provide commutators which produce a group of impulses arranged in a code manner, and I cause these commutators to repeat each group of impulses as frequently as is possible. In order that the code ring upon a telephone line may be repeated less frequently than my rapidly revolving commutators, I provide an auxiliary commutator. My auxiliary commutator is so designed and so connected in the circuits of the ringing devices that it permits the operation from time to time of one group of the code impulses, withholding the operation of the intervening repetitions of the group. I do this by connecting in series in a single circuit the fast and the slow commutators, and so associating the commutators that the slow commutator will be closed during one cycle of the fast commutator and be open for a predetermined number of succeeding cycles.

I provide also in the pilot switch two ringing positions. In the first ringing position, the fast commutators are effective to ring at all times; and I provide means for permitting the pilot switch to remain in this position during one and one only cycle of the fast commutators, thus attaining a single initial code ring, with a minimum of delay before the first ring.

(H) In my improved system of controlling circuits I provide four stop positions for the pilot switch in which the further movement of the pilot switch, and therefore the entire command of the connection, is under control of either of the two connected telephones. In the first position, pilot stop No. 9, the lifting of either telephone from the hook will advance the pilot. The next position, pilot stop No. 10, is held when the A-line telephone is off the hook and the B-line telephone is on the hook. The third position, pilot stop No. 11, is held when the A-line telephone is on the hook and the B-line telephone is off the hook. The fourth position, pilot stop No. 12, is held by both telephones off the hook and the pilot switch is advanced by hanging up either telephone. Advantages are obtained by the control of visual signals indicating the condition of the connection, and advantages are found in the complete system of control by which connection at all times is under complete control by either telephone without any operations other than the usual hook switch operations common in either automatic or manual telephone usage.

(K) In association with a connective division, I provide a set of signal lamps and a system of lamp signals by which the condition of the connective division may be known. These lamps are mounted prominently upon the frames supporting the switches and in such manner that an at-

tendant seated in a supervising position may see from the one view point all the lamps of a central office or of his portion of a central office. In connection with this plan, my system of lamp signals is such that the attendant by watching the lamp signals may know to a very considerable degree the progress made by any call which is received by the central office apparatus. I provide three lamps, and a normal call normally handled by the central office apparatus will produce illuminations of these lamps, or two of them, in a predetermined order and of predetermined duration which may be recognized visually by the attendant as indicating a connective division and a telephone user both acting in a normal manner.

While a call terminating upon a line previously engaged (the call therefore being defeated because of the guard or busy test upon the called line) may be considered in some ways as a normal call, I provide such details in my system of lamp signals and circuits that the sequence of signals produced when calling an engaged line is different from the sequence of signals produced when calling an idle line. By this detail of improvement, an attendant watching the lamps of a distant operating division, may know whether the call is terminated upon an idle or a busy selected line.

I provide also a signal which is displayed when the subscriber upon the B-line of the connection lifts his receiver before the lifting of the receiver upon the A-line. This is a condition having a peculiar interest in an automatic exchange of the character herein described. My improved signal for this condition also has a peculiar interest in that for the display of this signal I cause to glow simultaneously two lamps, neither of which indicates when glowing alone any part of the condition indicated when both glow simultaneously.

Two lamps are provided to indicate normal operation of switches and the third lamp is provided as an alarm lamp indicating an abnormal delay in the operation of the switches whether upon the part of central office devices or upon the part of the telephone users.

(M) For the detection of automatic switches operating abnormally, a timing device which is the equivalent of a slowly acting relay may be used, the device being so adjusted that it will become operative as soon as an automatic switch becomes operative and that it will become inoperative when the automatic switch reaches its normal position or any predetermined position. The relay contacts may be connected in an alarm circuit or in a circuit to restore the automatic switch to normal. The speed of operation of the slow relay or timing device

then may be adjusted to give the automatic

switch a sufficient interval to operate in normal manner before the timing device closes its contact points. By means of such a device, an automatic switch may be brought to the attention of an attendant by means of the alarm when the switch is not operating in normal manner or at normal speed; or, on the other hand, an automatic switch may be caused always to return to normal in readiness for further service, in case it has not operated in normal manner and at normal speed.

(N) I also combine in one device the functions of an alarm timer and a release timer.

I provide in my improved timer, two pairs of electrical contact springs, and I provide a moving striker driven step by step toward the springs. I so place the springs with reference to the striker that the striker engages and closes the first pair of springs upon a predetermined step and I so place the second pair of springs that upon the next succeeding or some predetermined succeeding step, the striker will engage and close second pair of springs either directly or by moving the first pair of springs or contact members to engage the second pair.

I thus cause my improved timer to close two circuits, each having a predetermined delay after the beginning of operation of the timer, one circuit having a greater delay than the other if desired. It is obvious that both circuits may be closed simultaneously if desired as an alternative method of operation.

By means of the delay of the second closing after the first, I am enabled to connect my timer contact points, so that an abnormal action of an automatic switch is first indicated by an alarm and later is relieved automatically by restoration of the switch, or I may provide an automatic release and cause an alarm later if the automatic release is not effective.

(P) When an automatic exchange is fully supervised, as in the busy hours of the day, it may be desired that every case of abnormal action be studied by the attendant and that no automatic releasing be permitted, all abnormal switches being released and restored manually by the attendant; in such a case it is desirable that the automatic release circuits of the timers be disabled. When the automatic exchange is unattended as at night and on holidays, the alarm circuits associated with automatic releasing devices have no practical value and may be disabled, leaving the normalizing of the automatic switches wholly to the care of the timer-controlled releasing circuits. It is obvious, however, that the exchange should not be left at any time without either alarm or release circuits operative.

I provide in connection with my improved

lamp-and-release timer, a manual night switch or lamp-and-release switch having two positions, in one position disabling the releasing circuits of the entire exchange, in the other position disabling the lamp-alarm circuits of the entire exchange. I provide such circuits for the alarm that they may be connected to a single bus wire, and then carry that bus wire through the night switch. In like manner I provide such a circuit for the release circuits of all the timer devices that they may be collected upon a single bus wire, and then carry that bus wire through the night switch.

(Q) Upon the seventh level of the pilot switch (Fig. 2), I provide a multiple brush comprising four movable contact points or brush fingers (paragraph Q) resting upon four of the fixed contact points of the level. These brushes in their progress connect together four points at all times, being four points determined at any time by the position of the brushes. At times, as in the normal position, no circuit is closed by the brushes since all four rest upon points connected to the same wire. At other times, as in number 3 stop position, two circuits are closed, 127-128 and 127-159. In another instance, number 11 stop position, three circuits are closed, 127-128, 127-159 and 127-154. By this arrangement of brushes and circuits, I secure in a single level of fixed contact points, the advantages of two or even three levels of contact points in that, I close upon the same level frequently two and in one instance, three simultaneous circuits.

(R) For a still further economy of the fixed contact points of an automatic switch, that a number of circuits greater than the number of levels of the switch may be obtained, I have provided upon the third level of the pilot switch of Fig. 2, two multiple brushes each of two brush points and each such multiple brush engaging two fixed points of the cylinder. In the operation of these brushes, the wires 114 and 188 are connected by the main brushes until the main brushes leave the point 14X3, being then connected by the auxiliary brushes. Thus while the auxiliary brushes are holding closed the path named, the main brushes are free to close the additional circuit 109-151 upon point 20X3 and 21X3. Thus, two independent circuits are closed by two independent pairs of brushes upon a single level of fixed contact points of the automatic switch. A further feature may be noted in that the circuit 109-151 is closed effectively twice in the cycle of operations of the pilot switch through the same fixed points 20X3 and 21X3, being closed by the main brushes when between stop position No. 9 and stop position No. 10 and being closed again by the auxiliary brushes immediately after the

main brushes leave stop position No. 14. As the switching capacity of such an automatic switch is limited in number of simultaneous circuits by the number of fixed contact points, the utility of increasing the number of simultaneous circuits without increasing the number of fixed contact points, is evident.

(SA) At times the switches in an automatic exchange are noted to be off-normal. It is not necessary to go at length into the reasons why or the conditions under which such switches attain an off-normal condition, when not actually in use in promoting or maintaining a telephone conversation. The purpose of the present invention is to accept the off-normal condition of the automatic switches and to restore them to normal condition in readiness for further service, restoration being attained automatically.

In a connective division of the type herein described, when a telephone call is initiated, the pilot switch is set off-normal and immediately the primary connector is set off-normal, the switches then co-operating with each other and with other switches to set up a connection. To maintain the connection, both the A-switch and the pilot switch must retain off-normal positions. If either the pilot switch or the A-switch return to normal, it is obvious that the other switch should be returned to normal promptly, and the signal controller and interconnector as well, in order that the entire division may attain its normal position of idleness in readiness for further service upon another call. I provide a system of circuits interconnecting the pilot switch and the A-switch such that the return of either to normal will return the other to normal also.

(SB) In the processes of restoring to normal a connective division, it is required sometimes to care for the condition in which the primary connector is not connected to any line but has passed to its 31st or to its normal position in either of which positions it is not associated with a telephone line. A circuit (70th), is provided for advancing the A-switch to normal. When the pilot switch reaches its first stop position in which it ordinarily would be placed under control of a calling telephone line over circuits passing through the A-switch, it is controlled automatically to restore its division to normal, the control being effected by a central office circuit local to the division and passing through normal points of the A-switch. The A-switch thus automatically substitutes a local control circuit for the line circuit when for any cause it is returned to normal at a time when it should occupy a line-selecting position.

(SC) When the pilot switch reaches normal and at all times when in its normal position, it closes a restoring circuit for the

5 A-switch extending through all off-normal stop positions of the A-switch, but being open in the A-switch when that switch is normal. It closes also a similar circuit for the signal controller, both of these circuits restoring their switches to normal as soon as the pilot switch reaches normal, if for any reason either of the other switches is off-normal at that time.

10 (SD) In order that different lengths of time limit may be had, yet that the expense of but a single timing device may be incurred, I provide a stepping timer deriving its stepping impulses from a battery and 15 commutators; in connection with the timer, I provide two commutators, a fast one and a slow one, so that the timer may be driven either rapidly or slowly according as it is connected with the fast or slow commutator. 20 To associate it with either commutator at the proper time, I carry the timer drive circuit through the pilot switch and thence to either commutator or to neither, in accordance with the requirements of the connection 25 from time to time as determined by the position of the pilot brushes.

(SE) In providing the division starter with a timer, I carry the drive circuit of the timer through the sub-normal position of 30 the division starter in which position the starter is waiting for the started primary connector to pick up the calling line, and I release and restore the timer between the sub-normal stop positions and the next normal stop position of the starter. The timer points are connected to the starter clutch.

(SF) I provide a novel means for disabling the division starter at such times as all divisions are off-normal, which is to say 40 at such times as no idle division exists so that any action on the part of the starter would be futile.

I accomplish this result by providing a stop position for the starter brushes additional to those stop positions associated with the connective divisions, and I provide a circuit passing in multiple to all connective divisions by which any normal connective division will cause the starter to pass its 50 "out of service" position. When all divisions are busy and a call is received, the starter will move until it reaches its "out of service" position where it will stop and await the return of a connective division to normal. As soon as a connective division returns to normal, it will start the division starter (82nd circuit) from its "out of service" position and the starter will move immediately to the sub-normal starter position 55 corresponding to the now normal connective division, starting the division to serve the waiting call.

(SG) In all large systems of telephone switching, certain units of apparatus or 60 certain circuits are duplicated many times

and are used for the same purpose, any one being available for service when not engaged by prior use. In manual systems, duplicated trunks are used by manual selection but the manual operator is 70 prone to select the first of the group if idle. In automatic systems, the automatic selection sometimes compels the use of the first trunk, if idle, the nature of the selecting apparatus being such as to make it impossible to select another device so long as the first device remains eligible. It is obvious that if the first unit of duplicated apparatus be in any way defective to prevent the completion of a specific call, that 80 specific call might be repeated innumerable times, so long as it were not contemporaneous with another call having the same destination, and at every repetition the call would be defeated because of the compulsory selection of the defective unit of apparatus.

I provide a method of using duplicated apparatus or duplicated electrical circuits having a common destination, the units of apparatus being selected in rotation by successive calls, whether contemporaneous or discontinuous and whether independent calls or repetitions of the same call. Thus, with my improved method of selecting and operating duplicated apparatus, the repetition 95 of a call will not meet and use the same units of duplicated apparatus and if the first call shall have failed by reason of any defect in any unit of duplicated apparatus, its repetition will not fail in similar manner by 100 reason of encountering the same defective unit of duplicated apparatus.

I accomplish this desirable result by providing a false busy test condition.

Upon selecting for use the first unit of 105 apparatus, a fact busy is placed upon its guard elements so long as it remains in use. When its use is terminated and the apparatus using it has been disconnected, means provided by my invention continue the busy 110 condition upon its test elements, thus rendering a false busy test or false guard indefinitely upon that unit of apparatus when tested. The first unit of duplicated apparatus being thus busy, either fact or false, the 115 next operation requiring its use will encounter the busy test and will be compelled to select the next unit of the duplicated apparatus. This second unit while used will bear a fact busy and after its use has 120 been discontinued, it will bear a false busy, thus compelling the next test to pass to the third unit of duplicated apparatus. The successive units of duplicated apparatus thus will be guarded with a false busy test 125 until the last of them has been selected for service. In connection with the last, I provide releasing means for the false busy upon all the others. As soon as the last unit of the series of duplicated apparatus has 130

been selected for service, the false busy is removed from all others, but should any remain busy by fact, the fact busy is not disturbed. The next search for an idle unit of apparatus will select the first unit and after use will leave a false busy compelling the selection of a second unit and so on as before. The last unit of duplicated apparatus therefore becomes a control unit for releasing the false busy test from all other units.

I provide for the release of the false busy from all other units whenever a control unit is tested without regard to whether the control unit is idle or busy, the fact that it is tested being evidence that the rotation of service is complete and that the false busy should be removed to permit the operation of another sequence.

(SH) I find it most advantageous to divide a group of duplicated apparatus into two parts, the first part of which is equipped with devices for giving the false busy, the last unit of the first part being the control unit and the several devices of the second part being at all times free from false busy so that if idle in fact they may be selected in the order of arrangement of their testing terminals. This principle may be applied by using but a single unit as the second part of a group, the single unit or last unit of the group then being available for service when the test finds the control unit busy, immediately taking the last unit which presumably will be found idle and rendering all other idle units free from the false guard for the next succeeding test.

(SK) For the application of the methods just described, I may provide a relay for each unit of apparatus in the rotational group. The first unit of the group has a locking relay which places a false busy test condition upon the testing terminals of its unit of apparatus and which locks to a circuit passing through normally closed contact points of the relay of the control unit. The second and successive units, if any, operate likewise to place the false busy upon the testing terminals of their unit of apparatus and likewise lock over the same circuit to the points of the relay of the control unit. The relay of the control unit when tested, operates only to break the locking circuit described and to unlock all the relays of all the other units of the rotational group.

55 I am not limited to the use of relays in this detail, as a cylinder switch may accomplish similar results.

As applied to manual practice, the use of any duplicated unit other than the control, 60 will lock that unit to the control, the units not necessarily being used in rotation.

As a modification especially adapted for manual practice, the control relay may be operated from terminals analogous to the 65 test terminals of a unit of apparatus but

having no function other than the control function for the release of the false busy. I term this a "dummy" control trunk.

(SM) In designing a system of registering calls or conversations upon central office meters in automatic exchanges having a pilot switch, I have designed a pilot switch occupying one position while the call bell of the selected or B-line is being rung and occupying another position during conversation. Accessible by the movable brushes of the pilot switch between these two positions, I provide contact points having their circuit path transiently closed by the pilot brushes while the brushes move from ringing position to talking position. This metering path I provide with a source of current and I take it through the meter of the calling line or A-line, thus completing the metering circuit.

To render an A-line meter operative if the B-line responds and inoperative if the B-line does not respond, I carry the metering circuit through the movable and front contact points of a relay which is charged by the B-line when a station of that line answers the ring. Thus, while the pilot brushes may advance from ringing to talking position without the answering of the B-line, no registration upon the A-line meter will be effected by such movement and only answered calls will be registered, since the relay mentioned will be uncharged at the time of the brush movement.

(SN) In connection with metering systems, it is desired sometimes that lines for fire department, police department, the telephone company's officers and even newspapers and doctors or special lines of any description shall be permitted to receive calls originating anywhere in the exchange without causing registration upon the meter of any line calling one of these "free service" lines. It is desired further at times that a line may be changed to such a "free service" without changing the directory number of the line. It is obvious that if a line is to have free service in the sense that no charge is to be made for calls originating upon it, the result may be attained by omitting the meter from the line or ignoring the meter. However, when it is desired that no charge shall be made for calls terminating upon a specified line, even though those calls may originate upon lines equipped with automatic meter devices, I provide such a system of control as will enable the specified line to react upon the metering circuit of the connective division and the metering apparatus of the calling line in such manner as to prohibit its normal operation. In connection with a pilot switch as described, I provide two relays connected with the selected line or B-line, the first of which closes the meter circuit and the second of which

- causes the pilot brushes to advance; the second relay thus causes the metering circuit to be closed through the first relay while the brushes are moving. In connection with 5 "free service" lines, I provide a reactive circuit which charges the second relay but not the first and thus advances the pilot switch from ringing to talking position while the first relay is still uncharged so 10 that the metering circuit through the pilot brushes at the time the pilot brushes are passing their meter contact point will be open in the contact points of the first relay and no operation of the meter will ensue. 15 After the talking position has been reached by the pilot switch, the charging of the first relay may be permitted since it cannot affect the meter.

In manual practice the same effect may be 20 accomplished by providing interfering or interlocking relays, such, that if the first relay be charged before the second, the meter will be operated, while if the second relay be charged before the first, the meter will not be operated. In this case it becomes immaterial with respect to the meter whether the remaining relay becomes charged or not.

(S. P.) To enable the toll operator to speak upon a line already in use for conversation, I provide a means for enabling a trunk from manual toll board to automatic switchboard to gain access to a selected line even though the selected line be in use and guarded by the usual busy test 35 condition.

The system as a whole is so organized that when a tested selected line is found to be previously engaged, one of the several switches of the connective division retains 40 a preliminary position and does not move to its ultimate talking position. By retaining this preliminary position, it accomplishes two purposes; it prevents connection of the calling line with the selected line, and it re- 45 turns a busy tone to the calling line.

I provide a means in connection with trunks from a manual toll board to an automatic switchboard whereby the said switch may be advanced from its preliminary to its talking position by a manual act of the operator of the manual switchboard when the busy tone is heard upon a trunk.

(S. Q.) The feature in which the party 55 line telephone differs from the telephone for the exclusive line is found in the presence of an additional step in the signal transmitter, which additional step has its utility in preventing the closing of the telephone speech bridge until after the reverting ring has been made upon the line in case of a reverting call.

(S. R.) I have not made any effort to prevent a second telephone user upon a party 60 line from listening to a conversation by a

first user of his line, my interference device acting only to prevent a second telephone user upon a party line from sending a call or operating his automatic call sender while a first user is upon the line in conversation. 70 My device comprises a blocking magnet for the call sender, which, when the line is in use for conversation, is operated upon the beginning of the movement of the call sender, to prevent the completion of the movement, and therefore to prevent the sending of a call upon a busy line. When the line is not in use for conversation, the blocking magnet is inoperative. 75

In the composite diagram shown by the combination of Figs. 1, 2, 3, 4, 5 and 6 there is illustrated a connective division which it may be determined is located upon the eighth section of the automatic central office; that is, upon the section serving lines having directory numbers 700-to-799. This is determined by observing that it is necessary to adjust the interconnector of Fig. 5 to have its register on the eighth step off-normal or upon the No. 7 set of points in the hundreds register to effect the connection to the trunk of four wires leading to the secondary connector of Fig. 6, which secondary connector has in its multiple points the same lines found in the primary connector of Fig. 1. 85

In describing the operation of the automatic telephone system herein shown, a typical call will be traced through the operations of setting up the connection, holding the conversation, and disrupting the connection. It will be assumed that line No. 714, being line No. 14 of Figs. 1, 6 and 7, is calling, and that the selected line is line No. 705. 90

For the purpose of describing the operation of meters and code ringing devices, it may be assumed from time to time that either or both of these lines may become lines equipped with any designated type of 105 substation equipment or circuit.

It will be assumed also that, at the beginning of the typical call to be traced, the several switches are idle and stand in the positions shown in the drawings. 115

The operation of my improved automatic telephone system is as follows:—

(1.) Primary adjustment.

The relay call finder (paragraph A) comprises two hundred and ten relays of which one hundred are line signal relays, one hundred are line cut off relays and ten (in the top row) are sequence relays, since each has the function at times of disabling certain 120 lines from calling while such sequence relay is charged, thus determining a sequence among lines calling contemporaneously. 125

By "calling" in connection with this division of the description, I refer to lines 130

which have initiated a call and have not yet been seized by a primary connector; that is, to lines holding their line signal relays charged, or attempting to do so. By "simultaneously calling" or "contemporaneously calling," I do not mean simultaneous initiation of a plurality of calls but the simultaneous or contemporaneous existence of a plurality of calls, probably successive in initiation, but overlapping in time between the closing of 1st circuit and 15th circuit for each of them.

The auxiliary relays or sequence relays are numbered (Fig. 7) 0-to-9. Line signal relays are numbered 00-to-09, 14, 21. Line cut-off relays are numbered 00'-to-09', 14', 21'.

Multipled through the left contact points of the line signal relays in horizontal rows are the decimal signal wires for the decimal digits 0-to-9; multiplied through the right contact points of the line signal relays in vertical rows are the units signal wires for the units digits 0-to-9. Minus bus wire or ground terminal of the main battery 200 is connected to the armature points both right and left of the line signal relays.

Upon the charging of any line signal relay by a calling line, its two armatures place earth or minus battery upon two wires, (1st) the decimal wire identifying the decimal digit of the calling line and leading to the decimal controller and (2nd) the units wire identifying the units digit of the calling line and leading to all the primary connectors of the section and leading also to one terminal of the winding of the sequence relay identified with the units of the calling line.

By the charging (1st circuit) of the line signal relay, a local circuit (2nd circuit) is closed from minus battery through the right armature of the line signal relay to the lower terminal of the winding of that sequence relay which is located directly above the line relay and through that helix to plus battery. Thus upon the institution of a call by any line, two relays are charged, namely, the line signal relay and then the corresponding sequence relay.

By the charging of the sequence relay, its right armature points are closed, placing minus battery upon the division starter clutch (3rd circuit) and starting the division starter brushes.

Also by the charging of the sequence relay, its left armature points are opened for the purpose of preventing confusion by two conflicting lines when calling contemporaneously.

The system of circuits and apparatus (paragraph B) for preventing confusion between two conflicting lines calling contemporaneously is as follows:—

With reference to lines having the same units digit: The apparatus of the decimal

registers and of the decimal controller will care for contemporaneous calls. The primary connector will adjust itself to the units position, which is the same for both or all of the calling lines, and the decimal controller then will send impulses adjusting the decimal register to some one of the lines, it is immaterial which. If two lines are calling before the decimal controller starts from normal, the decimal wire of the higher number will be engaged first and the decimal register will be adjusted to the line of the higher number. If it should occur that the line of the higher number should call at an instant after the decimal controller brush has passed its decimal wire, then the decimal controller will adjust the decimal register to the line of the lower number. In either case there will be no confusion, one of the lines will be picked up, and the remaining line will be served immediately by another connective division.

With reference to lines having different units digits: Confusion sometimes would result in the primary connectors and circuits as organized if several lines having different units were permitted to charge their line signal relays simultaneously. To avoid this, a series connection is made through the left armature contact points of the sequence relays in such manner that each sequence relay disables all lines to the right in the drawing, namely, all lines having higher units than the number represented by the charged sequence relay.

The precedence thus established among units would operate to discriminate against lines of the highest units. To avoid such discrimination the sequence is changed from time to time by the action of a sequence switch.

For economy in construction, the sequence switch is combined with the division starter (paragraph C), the lower six levels of the cylinder of Fig. 9 being the points of the sequence switch and the upper levels being those points having the functions of starting divisions.

When the starter is in stop position No. 1, it is in condition to start the first connective division of the section. When it is in its stop position No. 2 it is in condition to start the second connective division of the section and so on through the seven divisions, returning thence to the first division.

By a system of circuits involving the lower six levels of points in the starter cylinder, the sequence among units is changed as follows:—

With the starter brushes in stop position No. 1 or No. 2, ready to start either of the first two connective divisions, a path (1st circuit) is traced from plus battery through starter or sequence-switch points in 10th and 9th levels, wire 401 to all line signal

- relays of "0" units; branching through left contacts of sequence relay 0 to all line signal relays of "1" units; branching through left contact points of sequence relay 1 to all line signal relays of "2" units; branching through left contact points of sequence relay 2, wire 404, through starter points in 12th and 11th levels, through wire 403, to all line signal relays having "3" units; branching through left contact points of sequence relay 3 to all line signal relays having "4" units; branching through left contact points of sequence relay 4 to all line signal relays having "5" units; branching through left contact points of sequence relay 5, through wire 406, starter points in 14th and 13th levels, wire 405, to all line signal relays having "6" units; branching through left contact points of sequence relay 6 to all line signal relays having "7" units; branching through left contact points of sequence relay 7 to all line signal relays having "8" units; branching through left contact points of sequence relay 8, to all line signal relays having "9" units; branching through left contact points of sequence relay 9 to wire 402, to open points in the starter cylinder, in 10th level.

With the starter brushes in positions No. 30 1 or No. 2 the lines stand in a sequence in which "0" units come first, progressing through in order, and "9" units come last. In the case of lines of different units calling contemporaneously, the line having the lower units digit will charge its line signal relay, which will charge its corresponding sequence relay, which in turn by its left contact points will open the circuit of the line signal relay of the line having the higher units, so that the line having the higher units cannot charge any relay until after the line having the lower units has been taken by a primary connector. The order of precedence is 0, 1, 2, 3, 4, 5, 6, 7, 8, 9.

When the brushes of the starter have progressed as far as their stop positions No. 3 or No. 4, the sequence among the lines is changed.

Circuit (1st circuit) now extends from plus battery over starter points in 12th level, through brushes to points in 11th level, wire 403, to all line signal relays having "3" units; branching through left contact points of sequence relay 3 to all line signal relays having "4" units; branching through left contact points of sequence relay 4 to all line signal relays having "5" units; branching through left contact points of sequence relay 5, wire 406, starter points in 14th and 13th levels, wire 405, to all line signal relays having "6" units; then "7" units, then "8" units, then "9" units and as before over wire 402, to starter points in 10th level and continuing through starter brushes to starter 65 points in 9th level, wire 401, to line signal

relays having "0" units, then "1" units, then "2" units and to wire 404, which extends to open points in the starter.

Thus the sequence of lines when the 3rd or 4th connective division is to be started 70 will give precedence to units "3" and higher over units "0", units "1" and units "2" the order being 3, 4, 5, 6, 7, 8, 9, 0, 1, 2.

When the brushes of the starter have progressed as far as their stop positions No. 5, 75 No. 6, or No. 7, the sequence among lines will be changed again, the series circuit being as follows:—from plus battery, through points in 14th level of division starter, through brushes to points in 13th level, wire 80 405, sequence relays 6, 7, 8, 9, wire 402, starter points in 12th and 11th levels, wire 401, sequence relays 0, 1, 2, wire 404, starter points in 10th and 9th levels, wire 403, sequence relays 3, 4, 5 and wire 406, to open 85 points in 14th level of the starter.

When starting the 5th, 6th and 7th connective divisions, the lines therefore will have an order of precedence among units as follows, 6, 7, 8, 9, 0, 1, 2, 3, 4, 5. 90

Thus with the permuting arrangement of circuits through the sequence switch or starter, the lines having higher digits will not be discriminated against, since when two lines having high and low digits call contemporaneously, the machine switchboard sometimes will serve the higher number first and sometimes will serve the lower number first. With lines 11 and 99 calling at the same time, the 1st or 2nd connective 100 division would serve line 11 before line 99, while any one of the remaining five divisions would serve line 99 before line 11. With lines 33 and 99 calling simultaneously, the first four divisions would serve 33 before 99, while the last three divisions would 105 serve 99 before 33.

Assuming that a call has been initiated at telephone station No. 714 or at the apparatus shown in Fig. 10, the arm 242 will have been stepped forward one step by the telephone user in the ordinary manner of starting a call. The arm 242 now is in engagement with the pin 244 and a ground is placed upon line conductor 421, which conductor it is customary to name the "first" conductor of the line; the remaining conductor 422 in Fig. 10 is named the "second" conductor of the line. This will result in charging the line signal relay over first circuit, charging 115 the sequence relay over second circuit, starting the division starter over third circuit and starting the pilot of an idle division (assumed to be the first division) over 4th circuit, after which the primary connector 120 pertaining to the started pilot will be adjusted to connect with the calling line. 125

The 1st circuit (charging line signal relay) extends from the substation ground or minus battery terminal (Fig. 10) to pin 244, 130

arm 242, wire 421 (through Fig. 6 to Fig. 7), closed contact points of cut-off relay 14' and through helix of line signal relay 14 and from the upper terminal of that helix 5 to vertical bus wire common to ten line relays in a vertical row to (not through) closed left contact point of sequence relay 4 and branching to and through closed left contact points of sequence relay 3, wire 403, 10 starter points in 11th and 12th levels, wire 404, closed left contact points of sequence relays 2, 1, 0, wire 401, starter points in 9th and 10th levels, the starter brushes being on the first set of points as shown in the drawing, the first circuit then terminating upon wire 424 which is connected to plus battery. Current over first circuit charges line signal relay 14 which attracts its two armatures and closes second circuit. 15

20 The 2nd circuit (charging sequence relay) extends from minus battery, over wire 409, right closed contacts of charged line signal relay 14, vertical bus wire leading to lower terminal of sequence relay 4, through helix 25 of sequence relay 4 and to (not through) closed left contact point of sequence relay 4 and extending thence farther over the path traced for the circuit in the immediately preceding paragraph, and to plus battery. 30 Current over second circuit charges sequence relay 4 and that relay closes 3rd circuit.

35 The 3rd circuit (charging starter clutch) extends from minus battery (Fig. 8) over wire 420, wire 419, movable and back contact points of discharged relay 250, wire 407, (Fig. 7) right contact points now closed of charged sequence relay 4, wire 408 (Fig. 9), division starter cylinder points 1X3-4, wire 501, division starter clutch magnet, 40 wire 503, and to plus battery.

45 The division starter moves its brushes off of the first set of points, breaking 3rd circuit and causing the discharge of the starter clutch magnet. The starter brushes therefore stop in their next position, namely, their off-normal position on set No. 3 of points, and there close 4th circuit to start the pilot switch of the selected division, assumed to be Division No. 1 shown in the 50 drawings.

50 The 4th circuit (charging pilot clutch in No. 1 stop position or normal pilot position) extends from minus battery (Fig. 9) over wire 418, division starter points 3X5-6, wire 55 121 (Fig. 2), pilot points 1X14-2X14, wire 192, pilot clutch magnet 215 and to plus battery. Current over this circuit charges the pilot clutch magnet.

60 The pilot switch moves its brushes from its first set of contact points breaking the 4th circuit just described and discharging the pilot clutch magnet 215. The pilot brushes stop on their stop position No. 2 occupying the third and fourth sets of points 65 with the brushes which were normally upon

the first and second sets of points. The pilot thus closes 5th circuit to start the primary connector.

The 5th circuit (charging primary connector clutch through pilot points in No. 2 70 position) extends from minus battery (Fig. 3) over left movable and back contact points of uncharged relay 201, wire 102 (Fig. 2), pilot points 3X10-11, wire 186 (Fig. 1) primary connector clutch magnet 216 and to 75 plus battery.

Current over 5th circuit charges the primary connector clutch magnet and starts the cylinder brushes of the primary connector (sometimes called the A-switch 80 because it serves to associate the apparatus of the connective division with the A-line or call-originating line of a completed connection and conversation) which brushes then will move continuously until stopped by action of 6th circuit, or units-searching circuit, which operates to break 5th circuit by charging relay 201.

85 The moving brushes 233 and 234 in the A-switch which are bridged together by a conductor from the second quadrant to the fourth quadrant in the first level of the cylinder of the A-switch, now connect the collector segment of the fourth quadrant to the units signal wires 450 to 459 successively 95 until 6th circuit is formed.

90 The 6th circuit (charging relay 201 to stop primary connector cylinder brushes) extends from minus battery over wire 409 (Fig. 7) to right contact points now closed 100 of line signal relay 14, wire 454 (Fig. 1) and to cylinder point 17X1 of the A-switch, being extended when the moving brush 233 reaches point 17X1, from point 17X1 over the moving brushes to point 39X1, wire 115 105 (Fig. 2) pilot points 3X2-4X2, wire 101 (Fig. 3), helix of relay 201 and to plus battery. Relay 201 is charged by current over 110 6th circuit and, by attracting its armature, it breaks 5th circuit, discharging primary 115 connector clutch 216 and stopping all of the primary cylinder brushes, the brushes of the primary cylinder thus being brought to rest on sets of points numbers 6, 17, 28 and 39 respectively.

115 The pilot brushes in No. 2 stop position also close 7th circuit to start the decimal controller. The 5th and 7th circuits operate simultaneously.

120 The 7th circuit (charging decimal controller clutch through pilot points) extends from minus battery (Fig. 3) over points of relay 201, wire 102 (Fig. 2), pilot points 3X13-12, wire 123 (Fig. 8) decimal controller clutch magnet 217, and to plus battery.

125 Current over 7th circuit charges the decimal controller clutch and starts the brushes of the controller from their normal position, after which they will move continuously un- 130

til they reach their off-normal position, regardless of the continuance or discontinuance of 7th circuit just described. While the decimal controller brushes are moving 5 and before they reach their off-normal stop position with one brush on small segment 230, 7th circuit will have been interrupted by the charging of relay 201 over 6th circuit. In thus moving, the decimal controller 10 brushes institute a search for the decimal wire which identifies the calling line, the searching circuit being 8th circuit.

The 8th circuit (charging decimal relay 250 when identified decimal wire is found) 15 extends from plus battery (Fig. 8) over wire 410, through left helix of relay 250 to the long segment and bridged brushes of the decimal controller. In the progress of the brushes, the path thus far traced is connected 20 successively with the decimal wires 439, 438, 437 and so on until the identified wire is engaged, which in turn identifies the decimal digit of the calling line. In the assumed case, it is decimal wire 431 serving line 14. When this wire is engaged, the 8th circuit is completed and extends as follows: from minus battery (Fig. 7) wire 409, left contact points now closed of line signal relay 14, wire 431 (Fig. 8) small segment of decimal controller commutator, bridged brushes and large segment 232, wire 413, left helix of relay 250, wire 410 and to plus battery. Current over 8th circuit charges the relay 250 which locks itself over 9th circuit. 25

The 9th circuit (locking relay 250) extends from minus battery (Fig. 8) over wire 420, wire 419, movable and front contact points (now closed) of relay 250, wire 505, left helix of relay 250, wire 410 and to plus battery. 30

In the continuance of the movement of the decimal controller brushes, the decimal impulses are sent over 10th circuit to the decimal register of the started division.

The 10th circuit (charging decimal register by decimal impulses) extends from minus battery (Fig. 8) over wire 420, wire 419, closed movable and front contact points of charged relay 250, wire 505, wire 413, long segment 232 and brushes of decimal controller, and thence as a separate impulse over each of the small segments connected to the wire 129 and located at the right of the small segment identifying the decimal 45 digit of the calling line, over wire 129 (Fig. 2), pilot points 4X1-3X1, wire 119 (Fig. 1) collector segment in third quadrant, of first level of A-switch cylinder, moving brush in third quadrant, to the register magnet 214, moving brush in first quadrant, cylinder 50 points of collector segment first quadrant top level of cylinder, and to plus battery. By these impulses over 10th circuit, the decimal register of the primary connector or 55 A-switch is adjusted to its proper position

for the selection of the calling line. In the instance assumed, two impulses are received by the magnet 214.

When the brushes of the decimal controller reach their off-normal position with the right hand brush upon small segment 230, they come to rest and close 11th circuit to move the pilot switch brushes from their No. 2 stop position. 70

The 11th circuit (charging pilot clutch 75 through No. 2 position) extends from minus battery (Fig. 8) over wire 420, wire 419, closed contact points of charged relay 250, wire 505, wire 413, segment 232, brushes and segment 230 of decimal controller, wire 122 (Fig. 2) pilot points 3X14-4X14, wire 192, pilot clutch magnet 215 and to plus battery. 80

Current over 11th circuit charges the pilot clutch and the pilot brushes move from 85 No. 2 stop position, breaking 11th circuit just described, and then stop in No. 3 stop position, engaging the sixth and seventh sets of pilot points. The 5th, 6th, 7th, 10th and 11th circuits are interrupted by the pilot 90 brushes in leaving No. 2 position. In No. 3 position the 12th circuit is closed to move the division starter brushes from off-normal to their next normal position. 95

The 12th circuit (charging clutch of off-normal division starter through off-normal pilot points) extends from minus battery (Fig. 8) over wire 420, wire 127 (Fig. 2) pilot points 39X7-7X7, wire 128 (Fig. 9), division starter points 3X3-4, wire 501, division starter clutch magnet 218, wire 503 and to plus battery. 100

Current over 12th circuit charges the starter clutch and moves the starter brushes from points No. 3 to points No. 5, interrupting 12th circuit just traced. On next normal position of starter brushes, points 105 No. 5, 13th circuit is closed to restore the decimal controller to normal.

The 13th circuit (charging clutch of off-normal decimal controller) extends from minus battery (Fig. 8) over wire 420, wire 419, closed points of charged relay 250, wire 505, wire 413, large segment 232, bridged brushes of decimal controller, small segment 230, wire 122, wire 415 (Fig. 9) division starter points 5X1-2, wire 416 (Fig. 8) wire 123, clutch magnet 217 and to plus battery. 110

Current over 13th circuit charges decimal 115 controller clutch and the decimal controller brushes leave their off-normal position, breaking the 13th circuit and stopping in normal position where they close 14th circuit for release of relay 250. 120

The 14th circuit (discharging decimal relay 250) extends from minus battery (Fig. 8) over wire 420, wire 419, closed points of charged relay 250, wire 505, wire 413, segment 232, normal brushes, segment 231, 125

wire 414, right helix of relay 250, wire 410, and to plus battery.

The magnetic effect produced upon the core of relay 250 by current over 14th circuit is equivalent in strength and opposed in direction to the magnetic effect produced upon that core by current over 9th circuit. The core therefore is neutralized magnetically and the armature is released, interrupting both 9th and 14th circuits and closing at relay 250 the path of 3rd circuit, subject to closure at the sequence relays for the actuation of the division starter on a subsequent call.

15 The pilot switch brushes in No. 3 position close 15th circuit to place the busy-test potential upon the guard wire of the calling line and to operate the cut-off relay 14' of that line.

20 The 15th circuit (A-line guard circuit) extends from minus battery (Fig. 7) over wire 409 to lower helix terminals of all line cut-off relays, through the helix of line cut-off relay 14' over the guard wire 423 individual to the line identified, to the guard point of the line (Fig. 1) in the A-switch, cylinder point 6X9, cylinder brush, decimal register point, third decimal register brush (which has been adjusted to that point) cylinder brush on 6th level in second quadrant, collector segment on 6th level in second quadrant, wire 114, pilot points 6X3-7X3, wire 188 (Fig. 3) resistance 211, and to plus battery.

35 Current over 15th circuit charges the cut-off relay 14', releases the line signal relay and sequence relay, and provides the A-line with a guard potential to prevent interference by connective devices.

40 (2) *Selective adjustments.*

By the acts described, the started connective division has connected with the calling line and is now at the service of the calling line, in readiness to connect that line with any desired line in the telephone exchange.

The next step in setting up a telephone connection is the transmission from the substation of the calling line of signals indicating a portion of the directory number of the line with which connection is desired, and in response to that transmission of signals the connective division selects a trunk line extending to auxiliary apparatus (a secondary connector or B-switch) at a point adjacent to the terminal of the line to be called: the next step is the transmission from substation of the calling line of signals indicating the remainder of the directory number of the line with which connection is desired, and in response to this second transmission of signals the connective division causes the said selected secondary connector or B-switch to connect with the line desired.

The cylinder brushes of the primary connector, having moved to the sixth vertical set of points, counting their normal resting place as the first set of points, now rest in connection with the calling line, or line No. 714, and through the decimal register brushes upon the No. 1 set of points the A-line conductors, 421, 422, with the A-line guard wire 423, are extended to the conductors 112, 113, 114, leading to the pilot switch.

The action to be covered by this part of the description is the reading or interpretation of the dial setting of the call sender of the calling telephone and the adjustment of 80 sundry automatic switches in accordance therewith.

In its No. 3 stop position, the pilot switch provides a path (18th circuit) for signal impulses from the signal controller to the call 85 sender of the calling telephone, a path (19th circuit) for signals from the call sender to the signal relay 201, a path (17th circuit) from the signal controller to the ringing register or thousands register, a path (21st 90 circuit) from the signal controller to the hundreds register, and paths (23rd and 24th circuits) for the control of the hundreds interconnector to effect its search for an idle trunk.

The 16th circuit (charging clutch of signal controller through pilot points in No. 3 stop position) extends from minus battery (Fig. 2) over wire 109, pilot points 7X13-12, wire 130 (Fig. 4) signal controller points 100 1X11-12, wire 511, wire 506, controller clutch magnet 213, and to plus battery.

Having its clutch thus charged, the signal controller moves its brushes, breaks 16 circuit just described, and stops its brushes 105 upon its 43rd set of points. While moving, the signal controller brushes close 17th, 19th, 20th, 21st and 22nd circuits.

The 17-1st circuit (first impulse for register for first digit) extends from minus battery (Fig. 4) over wire 425, signal controller points 3X5-6, wire 131, (Fig. 2), pilot points 7X4-6X4, wire 195 ringing register magnet (or thousands register magnet), and to plus battery.

The 17th circuit (charging ringing register magnet for first directory digit) extends from minus battery (Fig. 3) over left movable and back contact points of relay 201, wire 432, (Fig. 4) signal controller points 120 5X5-6, wire 131, (Fig. 2) pilot points 7X4-6X4, wire 195, ringing register magnet 236, and to plus battery.

Each impulse over 17th circuit moves the four brushes 311, 312, 313, 314, of the ringing register shown in Fig. 2 just above the pilot switch and labeled as a whole, 219. Each impulse moves the four brushes one step toward the right.

Impulses are sent over 17th circuit from 130

the successive signal controller points 5X6, 7X6, and so on, for a total of 10 impulses, including the impulse over 17-1st circuit, and so long as relay 201 remains uncharged.

5 The relay 201 is charged by the 19th circuit.

The 18th circuit (charging telephone call sender magnet) extends from plus battery (Fig. 4) over signal controller points 2X1-2, wire 132 (Fig. 2) pilot points 7X1-6X1, 10 wire 112 (Fig. 1) through A-switch as adjusted, line conductor 422 (Fig. 10) wire 426, through switch 247 (now closed) through telephone magnet 248 and to earth or minus battery.

15 This circuit is continued on controller points 3X1-2 and 4X1-2, and is repeated in impulses on the successive controller points 6X2 and so on, and charges the telephone magnet twenty times while the signal controller brushes are moving from the first set to the 43rd set of points, that is, from normal position to their off-normal stop position.

20 The 19th circuit (signaling from telephone call sender) extends from substation earth or minus battery, through the telephone's call sender, only when 18th circuit is closed. When 18th circuit is closed, magnet 248 is charged, and arm 242 may rest upon one of the points 241 connected to indicator points 30 under indicator brushes 240. With magnet 248 uncharged, arm 242 rests upon black intermediate points, or upon points not connected to indicator points.

25 With 18th circuit closed and arm 242 resting upon a point 241 connected to an indicator point under an indicator brush 240, 19th circuit extends from substation earth connection, brush 240, pin 241, arm 242, wire 427, line wire 421, (Fig. 1) through the 40 A-switch, as adjusted to wire 113, (Fig. 2) pilot points 6X2-7X2 wire 101, (Fig. 3) helix of relay 201 and to plus battery.

35 When the circuit is closed the relay 201 interrupts 18th circuit and the relay 201 45 locks over 20th circuit.

The 20th circuit (locking relay 201) extends from minus battery (Fig. 4) over wire 425, signal controller 9th and 10th levels in first half of cylinder, wire 439 (Fig. 3), 50 right contact points of charged relay 201, wire 508, helix of relay 201, and to plus battery. The 20th circuit is broken as the signal controller brushes leave their 21st set of points, releasing relay 201 in preparation 55 for the transmission of signals to the hundreds register, over 21st circuit.

The 21st circuit (charging hundreds register for second directory digit) extends from minus battery (Fig. 3) over left movable 60 and back contact points of discharged relay 201, wire 432, (Fig. 4) controller points 23X5-6, wire 138, pilot points 7X11-10, wire 147, (Fig. 5) interconnector point 23X1, cylinder brush, hundreds register magnet 235,

interconnector normal switch, and to plus 65 battery.

The 21st circuit is repeated in impulses for ten impulses, or until the charging of the signal relay 201 by a repetition of 18th circuit.

70 The 22nd circuit (locking relay 201) extends from minus battery (Fig. 4) over wire 425, signal controller points on 9th and 10th levels in second half of cylinder, wire 439, (Fig. 3) right contact points of charged relay 201, wire 508, helix of relay 201, and to plus battery. The 22nd circuit is broken as 75 the signal controller brushes leave their 41st set of points.

80 At this stage of the process of setting up the connection, it becomes necessary for the interconnector to select and seize an idle secondary connector. For this search and seizure I provide novel busy-test circuits, (paragraph D.), extending the influence of the act 85 of testing to test for the normal or off-normal position of the secondary connector rather than for the engaged or disengaged condition of the conductors leading to the switch. At the same time, I effect the desired result with but the usual four conductors leading to the secondary connector, with but the usual three points per line in the secondary connector, and with the use 90 of but one battery.

95 In applying my invention I take three taps from the battery 200, two terminal taps, plus and minus, and an intermediate tap over the conductor 400, (Fig. 11). I provide an off-normal switch 237, which isolates 100 the test conductor 444 from the battery when the B-switch is normal and when off-normal connects the test conductor 444 to plus battery through an operating magnet 238. By applying minus battery at the interconnector terminals of the test conductor 444 105 (to 141, and for example through pilot points 29X12-13 when brushes are in No. 13 stop position, to wire 109 and to minus battery for release of the B-switch) the magnet 238 may be operated as desired. In this way 110 the test conductor 444 bears sometimes the plus potential through the magnet 238 and sometimes the minus potential from pilot point 29X12 or 10X10, the B-switch being 115 busy in either case. To test in such manner that the busy condition may be shown in either case, I connect my test relay 203 from the test wire 444 to the median-potential 120 wire 400 (23rd circuit) so that the test relay becomes charged from either the plus or minus potential of the test wire 444 and may remain uncharged from 444 only when 444 is isolated from the main battery by the open 125 position of the off-normal switch 273 as caused and held by the normal B-switch in its normal position of readiness for service.

Associated with 23rd or testing circuit,

24th circuit operates to initiate the searching movement of the interconnector and to continue that movement whenever a B-switch is engaged which tests busy by the test of 5 23rd circuit.

The 23rd circuit (interconnector's search) extends from 20-volt tap of 30-volt plus battery, or two-thirds pressure over wire 400 (Fig. 2), pilot points 40X9-39X9, wire 175 10 (Fig. 3), helix of relay 203, wires 521 and 107 (Fig. 2) pilot points 6X11-10, wire 141, (Fig. 5), interconnector point 12X2, bridged brushes to interconnector point 23X2, and to minus battery. This circuit charges relay 15 203 as soon as the pilot switch reaches its No. 3 stop position.

The 24th circuit (charging interconnector clutch) extends from minus battery (Fig. 4) over wire 425, controller points 43X9-10, 20 wire 434, (Fig. 3), right movable and front contact points of charged relay 203, wire 104, (Fig. 2) pilot points 6X5-7X5, wire 143 (Fig. 5), interconnector clutch magnet 219, and to plus battery.

25 The interconnector clutch thus is charged when the controller brushes reach 43rd set of points or off-normal stop position and the interconnector cylinder brushes are moved toward the right. The 24th circuit, which causes the brushes to move, passes through the contact points of relay 203, and, in moving the brushes, breaks the helix of relay 203, (23rd circuit) and discharges relay 203. At this time, while relay 203 is discharged, the 30 interconnector clutch dog is riding upon the edge of the clutch disk and the points of the first trunk to a secondary connector or B-switch are engaged before the dog drops into the notch corresponding to that trunk.

40 Assuming that the secondary connector or B-switch is busy, the 2nd variation of the 23rd circuit, or 23-2nd circuit, is formed (paragraph C).

The 23rd-2nd circuit (off-normal B- 45 switch) extends from 23rd circuit from wire 141 through the hundreds register as adjusted, through the moving cylinder brush of the interconnector switch to the wire 444 of the B-switch being tested, through the closed 50 off-normal points 237 of the B-switch, wire 514, clutch magnet 238, and to 30-volt plus battery. This circuit, by reason of its low potential (10 volts, or one-third full plus) and its high resistance, does not carry sufficient current to charge the B-clutch magnet to attract its armature, (it carries a current equivalent to about one-sixth the current normally taken by the B-clutch for operation of the clutch) but it charges the relay 55 203, which in turn charges the interconnector clutch magnet 219, continuing the movement of the interconnector brushes to engage the points of the next trunk.

Assuming that the secondary clutch mag- 60 net or B-clutch magnet is charged (in which

case minus battery is found upon wire 444 over 34th, circuit or 61st, circuit, which see,) at the time the 23rd circuit is closed to wire 444, then relay 203 will be charged over the 3rd variation of the 23rd circuit, or 23rd-3rd circuit.

The 23-3rd circuit (charged B-clutch) extends from minus battery encountered upon wire 444, through the moving interconnector brushes, wire 141, and so on, to the 20-volt (or two-thirds plus) potential upon pilot point 6X13, from wire 400. This charges relay 203 before the interconnector clutch dog drops into the notch corresponding to the B-switch being tested, and the interconnector brushes thus are carried to the next set of contact points, leading to the next B-switch.

The 23-1st circuit (normal B-switch) extends from 23rd circuit from wire 141, 25 through the moving interconnector switch to the wire 444 which is found open at the B-off-normal contact points 237 between wires 444 and 514. This pair of contact points will be found open when the B-switch is normal and will be found closed at all other times, being closed when either cylinder brushes or register brushes of the B-switch are off-normal, or both.

Relay 203 is not charged by the 1st variation of the 23rd circuit and the dog of the interconnector clutch drops into the notch corresponding to the B-switch tested.

An idle B-switch having been found thus, the first action is to set it off-normal to close 100 its test springs 237, thereby rendering it 105 busy by test to other selectors. This is done by 25th circuit and at the same time 26th circuit operates to start the pilot switch from its No. 3 stop position.

The 25th circuit (preliminary impulse for charging B-register) extends from minus battery (Fig. 4) over wire 425, controller points 43X9-10, wire 434 (Fig. 3) right movable and back contacts of discharged 110 relay 203, wire 435 (Fig. 5) closed contact points 251 of discharged interconnector clutch, wire 146 (Fig. 2) pilot points 7X6-6X6, wire 142 (Fig. 5), through interconnector as adjusted, wire 443 (Fig. 6) B- 115 switch cylinder point 12X6, B-cylinder brush, B-register brush third from top, B- 120 register point 1X3, wires 428 and 429, B- register magnet 252, wire 430 B-cylinder brush, B-cylinder point 23X1, and to plus battery.

The 25th circuit had not been closed before this idle B-switch was engaged because, when relay 203 was discharged, points 251 were open, and the reverse.

The 26th circuit (charging pilot clutch through No. 3 stop position) extends from minus battery (Fig. 4) over wire 425 controller points 43X9-10, wire 434 (Fig. 3), right movable and back contact points of 125

discharged relay 203, wire 435 (Fig. 5) interconnector clutch contact points 251 now closed, wire 146 (Fig. 2), pilot points 6X14-7X14, wire 192, pilot clutch magnet 215, and to plus battery.

In case the interconnector does not find an idle B-switch in its search, the pilot switch will be started from its No. 3 stop position over the 1st variation of the 26th circuit.

This circuit is closed by the movable member 254 passing between the two fixed members 353 and 353'.

The 26-1st circuit (charging pilot clutch through No. 3 stop position after unsuccessful interconnector search) extends from minus battery (Fig. 5) through contact points 353', 254, 353 which are closed by member 254 after the interconnector brushes have passed the last trunk position in the cylinder, then over wires 146', 146, (Fig. 2), pilot points 6X14-7X14, wire 192, pilot clutch magnet 215 and to plus battery.

The pilot brushes take their No. 4 stop position, occupying the points of the 8th and 9th sets. The signal controller now advances to its normal, in turn advancing the pilot switch to No. 5 pilot stop position, and then the signal controller begins its second revolution, in the course of which it adjusts the B-register and the B-cylinder in accordance with the setting of the call sender of the telephone line being served.

The 27th circuit (charging signal controller clutch through No. 4 pilot stop position) extends from minus battery (Fig. 2) over wire 109, pilot points 8X13-12, wire 133 (Fig. 4) controller points 43X11-12, wire 506, controller clutch magnet 213, and to plus battery.

The controller advances to its normal, with brushes on 1st set of points, as drawn in the figure, closing 28th circuit.

The 28th circuit (charging pilot clutch through No. 4 pilot stop position) extends from minus battery (Fig. 4) over wire 425, controller points 1X9-10, wire 134, (Fig. 2) pilot points 8X14-9X14, wire 192, pilot clutch magnet 215, and to plus battery. The pilot switch takes its No. 5 stop position with its brushes on the 10th and 11th sets of cylinder points, and closes the 29th circuit.

The 29th circuit (charging signal controller clutch through No. 5 pilot stop position) extends from minus battery (Fig. 2) over wire 109, pilot points 11X13-12, wire 130 (Fig. 4) controller points 1X11-12, wires 511 and 506, controller clutch magnet 213 and to plus battery.

The controller brushes move until they reach their 43rd set of points. In passing to normal, they have sent to the telephone call sender magnet 248, one impulse over 30th circuit, and in their second revolution they send a second set of impulses 20 in number, over 31st circuit.

The 30th circuit (supplementary to 31st circuit) extends from plus battery (Fig. 4) over signal controller points 44X1-2, wire 135 (Fig. 2) pilot points 8X5-9X5 (the pilot at this time being in No. 4 stop position), 70 wire 112 (Fig. 1), through A-switch as adjusted, line conductor 422 to the telephone, (Fig. 10), through wire 426, points 247 telephone magnet 248 and to earth or minus battery. This circuit is closed but once, furnishing but a single impulse. It is followed immediately by 31st circuit, similar to 18th circuit except in the pilot switch points.

The 31st circuit (charging telephone call sender magnet) extends from plus battery 80 (Fig. 4) over signal controller points 2X1-2, wire 132 (Fig. 2) pilot points 11X1-10X1, wire 112, (Fig. 1), through A-switch as adjusted, line conductor 422 to the telephone, (Fig. 10) and through telephone magnet 248 85 to earth or minus battery.

This circuit is repeated in impulses on the successive controller points giving twenty impulses and forming a total of twenty-one impulses for 30th and 31st circuits taken together.

The 32nd circuit (first impulse for B-register for third directory digit) extends from minus battery (Fig. 4) over wire 425, signal controller points 3X5-6, wire 131, (Fig. 2), 95 pilot points 10X4-11X4, wire 144, (Fig. 5), through interconnector switch as adjusted, wire 442, (Fig. 6) B-cylinder point 1X1, B-cylinder brush, wires 431 and 429, B-register magnet, 252, wire 430, B-cylinder brush, 100 B-cylinder point 23X1, and to plus battery.

The 32nd circuit (charging B-register for 3rd directory digit) extends from minus battery (Fig. 3) over left contact points of relay 201, wire 432, (Fig. 4) controller 105 points 5X5-6, wire 131, (Fig. 2) pilot points 10X4-11X4, wire 144, (Fig. 5) through interconnector as adjusted, wire 442, (Fig. 6), B-cylinder point 1X1, B-cylinder brush, wires 431 and 429, B-register magnet, 252, 110 wire 430, B-cylinder brush, B-cylinder point 23X1, and to plus battery. The impulses are sent over 32nd circuit until it is interrupted by relay 201, caused by current flowing over 33rd circuit.

The 33rd circuit (signaling from telephone call sender) extends from substation earth or minus battery (Fig. 10) through the telephone's call sender, only when 31st circuit is closed over elements 240, 241, 242, 120 427, then over line wire 421, (Fig. 1), through the A-switch as adjusted, wire 113, (Fig. 2), pilot points 10X2-11X2, wire 101, (Fig. 3) helix of relay 201 and to plus battery.

Relay 201 locks over 20th circuit, repeated, 125 (which see) and is discharged when the 20th circuit is broken as the signal controller brushes leave their 21st set of points.

The 34th circuit (charging B-clutch for 4th directory digit) extends from minus 130

battery (Fig. 3) over left contact points of discharged relay 201, wire 432, (Fig. 4) wire 513, 4th and 3rd levels in second half of signal controller, wire 136, (Fig. 2) pilot points 5 10X11-10, wire 141, (Fig. 5), through interconnector as adjusted, wire 444, (Fig. 6), through closed off-normal points 237 of B-switch, wire 514, B-clutch magnet 238 and to plus battery.

- 10 This circuit is closed continuously rather than by impulses and determines the B-switch cylinder adjustment by the duration of its closure, being equivalent to a set of impulses with the interstices closed. To render the angle of adjustment proper, the B-switch brushes are geared to one-half the speed of the controller brushes and pass but one set of points for each two sets passed by the controller brushes. The circuit is interrupted by relay 201, under the operation of 15 33rd circuit repeated, the relay 201 then locking over 22nd circuit repeated.

20 The directory switches, those taking adjustment by the directory number of the called line or B-line as indicated by the setting of the A-line call sender, and comprising the thousands or ringing register, the hundreds or interconnector register, the secondary or B-register and the secondary or B-cylinder, now have been adjusted. The B-switch now connects the three conductors of the B-line to conductors leading to the pilot switch.

35 (3) *Test and first ring.*

40 The next set of operations comprises the testing of the selected line to determine its busy or idle condition, the returning of the busy tone signal to the calling line if selected line be found busy, and the giving of a first signal ring upon the selected line if it be found idle.

45 The test of the selected line for busy (paragraph F) is made while the pilot switch is in motion between its No. 5 and No. 6 stop positions. The result of the test is recorded by the relay 204, in that when the pilot brushes reach their No. 6 stop position, the relay 204 will be found charged 50 or uncharged, according as the selected line has been found engaged or free. (Paragraph R.)

55 The 35th circuit (charging pilot clutch through No. 5 pilot stop position) extends from minus battery (Fig. 4) over controller points 43X9-10, wire 137 (Fig. 2) pilot points 10X14-11X14, pilot clutch magnet 215, and to plus battery.

60 This circuit is closed when the signal controller brushes in their second revolution reach their 43rd set of points, which is their off-normal stop position.

65 The pilot switch moves its brushes from its No. 5 stop position and stops them in their No. 6 stop position in engagement with

the 13th and 14th vertical sets of pilot points.

The 36th circuit (busy test upon idle line) extends from minus battery (Fig. 3) left to right, through helix of relay 204, wires 518 and 106, (Fig. 2), pilot points 12X6-13X6, wire 142, (Fig. 5), interconnector as adjusted, wire 443, (Fig. 6), B-switch as adjusted, to wire 423, or guard wire of the selected line. From the guard wire, if the selected line be free, 36th circuit extends to the cut-off relay helix and to minus battery (the point of beginning) furnishing no current to charge the relay 204.

The 36-1st circuit (busy test upon an engaged line) extends further from the guard wire 423 through the circuits of the guarding connective division, through points in its pilot switch, 3rd or 6th level, from No. 3 to No. 12 stop positions, through resistance 85 (as 211 or 212 of Fig. 3) and to plus battery. This variation of the 36th circuit charges relay 204, which locks over 37th circuit, and remains so locked when the pilot switch reaches its No. 6 stop position and until the pilot switch leaves its No. 6 stop position.

The 37th circuit (locking relay 204) extends from minus battery (Fig. 3) through the helix of relay 204, wire 522, closed left contact points of charged relay 204, wire 190, (Fig. 2), pilot points 12X10-11, wire 182, (Fig. 3) through resistance 212 and to plus battery.

Assuming that the selected line is found free (for the contrary assumption see 47th circuit and following), the relay 204 remains uncharged, the pilot switch reaches its No. 6 stop position and 38th circuit is closed to move the signal controller to normal.

The 38th circuit (charging signal controller clutch after test upon an idle line) extends from minus battery, (Fig. 3) over right movable and back contact points of uncharged relay 204, wire 105, pilot points 110 14X13-12, wire 133, (Fig. 4) signal controller points 43X11-12, wire 506, signal controller clutch magnet 213, and to plus battery.

The signal controller moves to normal position completing 39th, 40th, 41st, 43rd, 52nd and 16th circuits. The 39th circuit places guard potential upon the guard wire of the selected line, found idle. The 40th circuit moves the pilot switch to promote the next 120 action.

The 39th circuit (guard for B-line) extends from plus battery (Fig. 3) through resistance 212, and over wire 412, (Fig. 4), controller points 1X1-2, wire 156 (Fig. 2) 125 pilot points 15X6-16X6, wire 142, (Fig. 5), through interconnector as adjusted, wire 443, (Fig. 6), B-switch as adjusted, wire 423 of selected line (Fig. 7) through cut-off relay helix to wire 409 and to minus battery. Cur- 130

rent over 39th circuit charges the cut-off relay and establishes a guard condition upon the B-line, as soon as the pilot brushes reach their No. 7 stop position. The potential 5 upon the guard wire 423 of the B-line is about one-half that of the main battery 200, the resistance of the cut-off relay helix being about the same as that of the resistance element 212.

10 The 40th circuit (charging pilot clutch through No. 6 stop position and through signal controller after test upon an idle line) extends from minus battery (Fig. 4) over signal controller points 1X9-10, wire 134, 15 (Fig. 2), pilot points 13X14-14X14, wire 192, pilot clutch magnet 215, and to plus battery.

10 The pilot brushes move to their No. 7 stop position, engaging 15th and 16th sets of pilot 20 points, in which position they await the beginning of the next code ringing cycle as determined by the engagement of the commutator 276 with its brush, closing 41st circuit.

25 The selected line now is to be given a first ring by giving one code ring upon the B-line prior to the restoration of the call sender of the calling line to its normal position to permit the A-line hook to be raised. This is effected in the following order:

30 Pilot brushes in stop position No. 7 await the beginning of a code ringing cycle. Pilot brushes in stop position No. 8 close circuits to the A-line and B-line independently and 35 currents pass first to the B-line to ring its signal bell or bells according to code and then to the A-line to set its call sender forward to normal position. Pilot brushes then pass to No. 9 stop position and there await 40 the lifting of the hook lever of either calling or called station.

35 The 41st circuit (charging pilot clutch through No. 7 stop position before first ring) extends from minus battery (Fig. 3) 45 through commutator 276, wire 446, (Fig. 4), controller points 1X4-3, wire 181 (Fig. 2), thousands register or ringing register, lowest level of points, lowest brush 314 of that register, wire 198, pilot points 15X14-16X14, 50 wire 192, pilot clutch magnet 215, and to plus battery. The pilot brushes are advanced from No. 7 stop position into No. 8 stop position at an instant between code rings. In 55 their No. 8 stop position they engage the 17th and 18th sets of pilot points.

60 The 42nd circuit (charging ringing relay 205 through No. 8 pilot stop position for first ring) extends from minus battery (Fig. 3) through commutator 271, (Fig. 2), ringing register point 2nd from left 3rd from top, ringing register brush 313 adjusted upon 65 that point, wire 173, (Fig. 3), right to left through helix of relay 205, wire 108, (Fig. 2), pilot points 17X12-13 and to plus battery.

There are four variations from this circuit, the selection of one of the five circuits being determined by the position of the ringing register brushes, and current is taken through commutator 271, 272, 273, 274 or 70 275 according to the setting of the ringing register brushes. Each of the five variant circuits for the helix of relay 205 is closed in two positions of the ringing register brushes, and the two positions are distinguished from each other by the reversal of the wires 196-197 upon the upper two levels of ringing register points. The three brushes, 311, 312, 313, thus take ten combinations of ringing circuits by selecting at the 80 same time among the five variations of 42nd circuit and between the two variations of 43rd circuit.

75 The 43rd circuit (ringing B-station first ring) extends from the earth connection of 85 the ringing generator 210, (Fig. 3), over wire 197, (Fig. 2), ringing register point, ringing register brush, wire 172, (Fig. 3), right front and movable contact points of charged ringing relay 205, wire 438, (Fig. 90 4), signal controller points 1X8-7, wire 155, (Fig. 2), pilot points 17X5-18X5, wire 148, (Fig. 5), through interconnector switch as adjusted, wire 441, (Fig. 6) through B-switch as adjusted, line conductor 421 of 95 the B-line (Fig. 10), through the ringing bridge comprising ringer and condenser 245 and (if not a party line) returning over line conductor 422 (Fig. 6) through the B-switch as adjusted, wire 442, (Fig. 5) interconnector switch as adjusted, wire 144, Fig. 2, pilot points 17X4-18X4, wire 153, (Fig. 4) signal controller points 1X5-6, wire 437, (Fig. 3), left movable and front contact points of charged ringing relay 205, wire 100 171, top ringing register brush, ringing register point, wire 196, (Fig. 3) and to the generator of alternating ringing currents, 210.

105 The 43rd circuit has one variation as described above. For 43rd circuit, the ringing ground is applied to wire 421 of the line and the ringing current is passed over wire 422 to the party line bells. In the variation of the 43rd circuit, the ringing 115 ground is applied to wire 422 and the ringing current is passed over wire 421 to the party line bells. If the selected line be a party line with grounded bells, then the 120 bells will be rung selective in two groups by the selection of the 43rd circuit or its variation but if the selected line be a line with but one telephone and a bridged bell circuit from wire to wire, then the bell will be rung by either the 43rd circuit or its 125 variation.

120 The call sender arm 242 of Fig. 10 was advanced one full step, from 243 to 244, mechanically by the act of the telephone user in initiating the call. It has been ad- 130

vanced forty-one full steps, from 243 to 253, electromagnetically by forty-one impulses from the signal controller over 18th, 30th and 31st circuits. It now rests on point 253 and requires one final step to advance it to normal pin 243 to complete the talking bridge from 421 through 427, 242, 243 receiver, transmitter and 246 to 422.

The bell of the B-line being rung once as described, the call sender of the A-line is stepped to its normal or talking position by current over 44th circuit.

The 44th circuit (charging magnet of the calling telephone call sender over wire 422 after first ring) extends from earth or minus battery at the telephone (Fig. 10), through the call sender magnet 248, over wire 422, of the A-line (Fig. 1) through the A-switch as adjusted, wire 112, pilot points 18X1-17X1, wire 168, (Fig. 3), commutator 278 and the plus battery.

The final step of the call sender is effected by this current and the call sender passes to normal position, permitting the talking bridge to be closed.

In case the calling line is a party line, its telephone is that of Fig. 16 instead of Fig. 10. The differences are three: The ringer is from line wire to earth (Fig. 11) instead of from line wire to line wire (Fig. 10). The circle of pins 241 has two extra pins, 254 and its insulated companion between 254 and 243, the two extra pins providing one extra full step for the arm 242. The disk 250 is cut to open the switch 247 when arm 242 is upon either pin 290 or pin 243.

In case the calling line is a party line, its call sender (Fig. 12) has its arm 242 on sub-normal 253, and the arm 242 requires two full steps to advance it to its normal pin 243 to complete the talking bridge between the line wires.

At this time, with 242 upon 253, the switch 247 is closed and the magnet 248 is connected from line wire 422 to earth.

The 44th circuit as traced above, now operates to charge the magnet 248, which by attracting its armature advances the arm 242 from pin 253 and by releasing its armature advances the arm 242 into engagement with pin 290; by the movement of the arm 242 and its attached disk 250, the notch of 250 is brought under the bell-crank dog 249, and switch 247 is permitted to open. See Fig. 17.

The opening of the switch 247 removes the magnet 248 from line wire 422, and the closing of 242 and 290 connects the magnet 248 from earth to line wire 421, over the path 248, 417, 411, 290, 242, 427.

A final step of the arm 242 now is required, to advance it from pin 290 to pin 243. This, in the case of a party line is supplied over 45th circuit, the 45th circuit

being ineffective in the case of such a telephone as that of Fig. 10.

The 45th circuit (charging call sender magnet over wire 421 after first ring) extends from earth or minus battery at the telephone (Fig. 10) through the call sender magnet 248, over line wire 421 of the A-line (Fig. 1) through the A-switch as adjusted, wire 113, (Fig. 2), pilot points 18X2-17X2, wire 169 (Fig. 3) commutator 279 and to plus battery.

The circuits operative while the pilot switch is in its No. 8 stop position will be found equally effective in a reverting call where the B-switch is connected with the line already seized by the A-switch, that is to say, when the called station is upon the same line as the calling station and when the ringing currents of 43rd circuit pass over the same telephone line as the signal currents of 44th and 45th circuits.

When the first variation of the 43rd circuit is closed for ringing station 1, 2, 3, 4 or 5, the ringing ground is placed upon line wire 422 and the ringing currents pass over line wire 421 and through the bells to earth before the arm 242 of the calling station is advanced from pin 253. When the 43rd circuit is closed, the ringing ground is placed upon line wire 421 and the ringing currents are sent over line wire 422 upon which at that time the call sender magnet 248 is connected, as well as the ringing bridges to earth. The first impulse of ringing current will charge the call sender magnet 248 which, by action of the call sender arm 242, as described, will be removed from line wire 422 and transferred to line wire 421, while the call sender continues to hold the talking bridge open. The call signals then will be rung upon the bells connected from line wire 422 to earth, and upon the conclusion of the signals, 44th and 45th circuits will be closed. The 44th circuit will be ineffective since its functions have been accomplished by the first impulses over 43rd circuit. The 45th circuit then acts as described above.

By this means, the closing of the talking bridge of the calling station is delayed until after the first ring. In case the call is a reverting one, ringing back upon the calling line, the talking bridge of the calling telephone is not permitted to interfere with the ringing circuits or signals of the first ring.

The first ring having been accomplished, the pilot brushes leave their No. 8 stop position.

The 46th circuit (charging pilot clutch through No. 8 pilot stop position) extends from minus battery (Fig. 3) through commutator 277, wire 167, (Fig. 2) pilot points 17X14-18X14, wire 192, pilot clutch magnet 215 and to plus battery.

The pilot brushes leave their No. 8 stop position, thus preventing the repetition of the first code ring, and stop in their No. 9 stop position on 19th and 20th sets of pilot 5 points, in which position they await the removal of the receiver from the hook of either telephone. This action will be described under the headings of "Repetition of ring" and "Release".

19 Referring to 36th circuit and assuming that the tested line had been found engaged, the first variation of the 36th circuit would have resulted in charging the relay 204 when the moving pilot brushes were upon their 15 12th and 13th set of points, which is not a stop position, the signal controller brushes being then at rest upon their 43rd set of points. By the charging of the relay 204, under busy test condition, the 37th circuit 20 locks it.

25 Relay 204 being charged and locked, the pilot switch upon reaching its No. 6 stop position does not close 38th circuit to start the signal controller; the signal controller remains off-normal with its brushes on its 43rd set of points until after the pilot has passed talking position. (See 65th circuit).

30 As the signal controller does not pass to its normal position at this time, 39th circuit to pass the pilot switch from No. 6 stop position cannot be closed. Instead, the pilot is advanced by current over 47th circuit.

35 The 47th circuit (charging pilot clutch through No. 6 pilot stop position after test upon a busy line) extends from minus battery (Fig. 3) over right movable and front contact points of charged relay 204, wire 178 (Fig. 2) pilot points 18X12-13, wire 192, pilot clutch magnet 215 and to plus battery.

40 From the No. 7 stop position, 41st circuit advances the pilot switch into No. 8 stop position, 42nd circuit charges the ringing relay, 44th and 45th circuits operate the 45 call sender and 46th circuit passes the pilot brushes to their No. 9 stop position, thus concluding the cycle of operations incident to the first ring.

46 The 43rd circuit, in the case of a test upon 50 a busy line, extends from the two terminals of the ringing generator through the wires 196 and 197, through the upper two levels of the ringing register, through wires 171 and 172, closed contact points of charged 55 ringing relay 205 wires 437 and 438 to signal controller points 1X6 and 1X8, where the circuit is open because the signal controller brushes are off normal. At the same time, the tone circuit is closed to the calling 60 subscriber.

65 The 48th circuit (busy tone) extends from the busy-tone transformer 209, (Fig. 3), over wire 193, (Fig. 2), pilot points 21X11-10, wire 185, (Fig. 4), signal controller points 43X7-8, wires 433 (Fig. 3) and 107,

through condenser 256, to wires 101' and 101; also from the busy-tone transformer 209, over wire 194, pilot points 22X11-10, wire 184 (Fig. 4), controller points 43X5-6, wires 436 (Fig. 3) and 106', through condenser 255, to wires 103' and 103; from these points, 103 and 101, the two sides of the circuit may be traced over the 57th or talking circuit to the A-telephone.

70 In case the selected line is found busy by test, the signal controller brushes will remain upon their 43rd set of cylinder points while the pilot brushes are in their No. 7 stop position, closing a variation of 41st circuit whereby the wait of the calling telephone user may be shortened.

75 The 41-1st circuit (charging pilot clutch through No. 7 pilot stop position and controller off-normal points, before restoring the call sender to normal and after test upon a line busy by test) extends from minus battery (Fig. 3) through commutator 275, wire 165, 165', (Fig. 4), signal controller points 43X4-3, wire 181, (Fig. 2), ringing register points and brush, wire 198, pilot 80 points 15X14-16X14, wire 192, pilot clutch magnet 215 and to plus battery.

(4) Repetition of ring.

95 The first ring is given with a minimum delay after the selected line is found free. To do this with a minimum delay, the ringing cycle is repeated as frequently as possible, since the first ring must await the beginning 100 of the code cycle.

To repeat the ring at the frequency of recurrence of the code cycle as determined for the first ring would not be desirable. Therefore, I provide (paragraph G) fast 105 commutators 271, 272, 273, 274, 275, 276, 277, 278 and 279 at a speed of about 20 revolutions per minute, for the first ring, as described. I provide also an auxiliary or slow commutator, 270, having a speed of one 110 revolution for an integral number of revolutions of the fast commutators, and I provide it with but one segment of such an angular dimension that the time of closed circuit of commutator 270 equals or slightly 115 exceeds the total time of the closures of commutator 275, and therefore includes the time of closure of commutators 271, 272, 273 and 274.

120 The commutators 275 and 270 being geared together at (say) a ratio of 6-to-1, and being adjusted to begin their closures at the same time, the commutator 270 will remain closed continuously for one cycle of the effective periphery of commutator 275, 125 then will remain open for five such cycles. A circuit having these two commutators in series would receive the impulses determined by commutator 275 for one effective cycle, then would be held open by commutator 270 130

for the time of three complete cycles of commutator 275, when the action of commutator 275 would be repeated. Such a circuit is the 51st circuit. With commutator 275 at 20 revolutions per minute and 275 and 270 at 6-to-1, one complete code ring would be given every eighteen seconds.

With pilot switch in No. 9 stop position:

The A-station or calling telephone lifts the receiver from the hook and thereby closes 49th circuit.

The 49th circuit (current supply to A-line) extends from minus battery, (Fig. 3) left to right through helix of relay 202, wire 103, (Fig. 2) pilot points 20X1-19X1, wire 112, (Fig. 1), through A-switch as adjusted, wire 422 of the A-line, (Fig. 10) through the telephone bridge 246, 257, 258, 243, 242, 427, of the A-station, returning over line wire 421, (Fig. 1) through A-switch as adjusted, wire 113, (Fig. 2), pilot points 19X2-20X2, wire 101, (Fig. 3) and left to right through helix of relay 201 to plus battery. The relays 201 and 202 are charged, thereby closing 50th circuit for advancing the pilot switch.

The 50th circuit (charging pilot clutch through No. 9 stop position under control of A-line) extends from minus battery, (Fig. 2), pilot points 19X13-12, wire 179, (Fig. 3), left movable and front contact points of charged relay 202, wires 519 and 178, (Fig. 2), pilot points 19X14-20X14, wire 192, pilot clutch magnet 215 and to plus battery.

35 The pilot brushes move to No. 10 stop position in engagement with the 21st and 22nd sets of pilot points, in which position 51st circuit will ring upon the B-line periodically.

40 The 51st circuit (charging relay 205 for repeated ring) extends from minus battery (Fig. 3) through commutator 271, (or 272, 273, 274 or 275 as determined by the setting of the ringing register brushes) over wire 161, (Fig. 2), ringing register point, register brush, wire 173, (Fig. 3), right to left through helix of relay 205, wire 108 (Fig. 2), pilot points 10X9-11X9, (closed by the auxiliary brushes normally upon pilot points 50 34X9-35X9), wire 120, (Fig. 3), commutator 270 and to plus battery.

55 The periodic ringing continues as long as the pilot switch remains in No. 10 stop position.

(5) *Conversation and release.*

It is desirable that the connection established as described be under the control of either telephone to the connection, (paragraph H), for purposes of disruption of the connection and release of the lines.

60 Release of the lines and restoration of all operating apparatus to normal condition of disuse, awaiting further service, becomes automatic when the pilot switch reaches its No.

13 stop position. The pilot leaves its No. 9 position its No. 10 position, its No. 11 position and its No. 12 position under control of the telephones of the connected lines, and it is desired that either substation telephone be 70 able to control the pilot switch, and therefore to effect the discontinuance of the connection, in any of the pilot stop positions No. 9, No. 10, No. 11, or No. 12.

In the improved system of my invention 75 (paragraph H) either substation telephone may advance the pilot switch from any one of the four stop positions named, and therefore either substation telephone may advance the pilot switch from all of them, 80 from its first telephone-control stop position, No. 9, to its position of total automatic release, No. 13.

This is effected by attaining the following 85 conditions of control:

In pilot stop position No. 9: The lifting of either substation switch hook will advance the pilot switch to its stop position No. 10 or No. 11.

In pilot stop position No. 10 or No. 11: 90 Either of these stop positions may be held only by maintaining one sole telephone off the hook, the other remaining on the hook. The A-telephone off the hook holds the pilot in No. 10 stop position, the B-telephone off the hook holds the pilot in No. 11 stop position. By raising the remaining switchhook, the pilot switch is advanced to No. 12 stop position; by depressing the switchhook previously lifted, the pilot switch is advanced to No. 13 stop position. If both 100 telephones are lifted simultaneously when the pilot switch is in stop position No. 9, the pilot moves continuously from No. 9 to No. 12.

In pilot stop position No. 12: This stop position may be held only by keeping both 105 telephones off the hooks. The hanging up of either or both will advance the pilot switch to its No. 13 or automatic-restoration stop position. Hence, if the pilot has been advanced from No. 10 stop to No. 12 stop by hanging up the telephone originally lifted when in No. 9 stop position, the pilot will move continuously from No. 10 to No. 13 110 stop position.

In the four stop positions, Nos. 9, 10, 11 and 12 the telephone lines are connected through to their controlling relays, 201, 202, 203, 204. It is by means of these relays and 115 circuits and apparatus associated with their armatures, that the desired control features are attained. See Fig. 11 for simplified circuits.

While ringing periodically upon the B-line, the A-telephone is in readiness for 125 conversation, and awaits the response of the B-telephone.

When the B-station lifts the receiver from the hook, the 52nd circuit is closed through 130

that station, charging relays 203 and 204 and by the 53rd circuit advancing the pilot switch to No. 12 or talking position.

- 5 The 52nd circuit (current supply to B-line) extends from minus battery (Fig. 3) left to right through helix of relay 204, wire 518, left back and movable points of discharged relay 205, wire 437, (Fig. 4), signal controller points 1X6-5, wire 153, (Fig. 2), pilot points 22X4-21X4, wire 144, (Fig. 5), interconnector switch as adjusted, wire 442, (Fig. 6), B-switch as adjusted, line wire 422 of B-line, speech transmitting bridge of B-station, returning over line 10 wire 421 of B-line, through B-switch as adjusted, wire 441, interconnector switch as adjusted, wire 148, pilot points 22X5-21X5, wire 155, signal controlled points 1X7-8, wire 438, right movable and back contact 15 points of discharged relay 205, wire 521, left to right through helix of relay 203, wire 175, pilot points 22X9-21X9, and to plus battery. 20

Relay 204 charged by 52nd circuit, closes 53rd circuit.

- 25 The 53rd circuit (charging pilot clutch through No. 10 pilot stop position upon response of B-station) extends from minus battery (Fig. 3) over right movable and front contact points of charged relay 204, 30 wire 178, pilot points 21X14-22X14, wire 192, pilot clutch magnet 215, and to plus battery.

The 54th circuit becomes operative at this time, but will be discussed under the title 35 of "Special services, Meters."

- When the pilot brushes reach their No. 11 stop position with the A-telephone and B-telephone both off the hook, 55th circuit is closed to advance the pilot brushes 40 from the No. 11 stop position, passing the position without stepping.

- The 55th circuit (charging pilot clutch through No. 11 stop position with both telephone hooks up) extends from minus battery (Fig. 3) over right movable and front contact points of charged relay 204, wire 519, front and movable contacts of charged relay 202, wire 179, (Fig. 2), pilot points 23X12-13, wire 192, pilot clutch magnet 215 50 and to plus battery.

- When the pilot brushes reach their No. 12 stop position, in engagement with the 25th and 26th sets of pilot points, the 56th or talking circuit is formed.

- 55 The 56th circuit (talking) extends from the A-telephone over line wire 421, through the A-switch as adjusted, wire 113, pilot points 25X2-26X2, wire 101, (Fig. 3), wire 101', condenser 256 on the plus side of the 60 circuit, wires 107' and 107, right back and movable contact points of discharged ringing relay 205, wire 438, (Fig. 4), signal controller points 1X8-7, wire 155, (Fig. 2), pilot points 25X5-26X5, wire 148, (Fig. 5), interconnector switch as adjusted, wire 441,

(Fig. 6), B-switch as adjusted, line wire 441 of the B-line to the B-telephone; also from the A-telephone over line wire 422, through the A-switch as adjusted, wire 112, pilot points 25X1-26X1, wires 103 and 103', 70 through the condenser 255 on the minus side, wires 106' and 106, left back and movable contact points of discharged ringing relay 205, wire 437, signal controller points 1X6-5, wire 153, pilot points 26X4-25X4, 75 wire 144, interconnector switch as adjusted, wire 442, B-switch as adjusted, line wire 422 of the B-line, to the B-telephone.

Current supply for the transmitters is over 48th, 51st circuits traced through the 80 No. 12 pilot stop position.

After the close of the conversation, if the A-telephone hook lever be depressed, 48th circuit will be broken, relays 201 and 202 will be discharged and 57th circuit will be formed, charging the pilot clutch to pass the brushes from the No. 12 stop position to the No. 13 stop position, which is a position of automatic release and restoration.

The 57th circuit (charging pilot clutch through No. 12 stop position under control of A-station) extends from minus battery (Fig. 2) over wire 109, pilot points 25X13-12, wire 179, (Fig. 3), left movable and back contact points of discharged relay 202, wires 523 and 105, (Fig. 2) pilot points 25X14-26X14, wire 192, pilot clutch magnet 215, and to plus battery.

Variations in the signal circuits in the No. 9, No. 10, No. 11 and No. 12 pilot stop positions. 100

If, after conversation, with the pilot brushes in the No. 12 stop position, the B-telephone hook lever is depressed before 105 that of the A-telephone, the following circuit is formed:

The 57-1st circuit (charging pilot clutch through No. 12 stop position under control of B-station) extends from minus battery 110 (Fig. 3) over right movable and back contact points of discharged relay 204, wire 105, (Fig. 2), pilot points 25X14-26X14, wire 192, pilot clutch magnet 215, and to plus battery.

With the pilot switch in No. 9 stop position, the connective division awaits the lifting of either receiver from its hook, the pilot advancing under control of either of the two connected telephones. If the A-telephone lift the receiver, 49th circuit is closed, closing in turn 50th circuit and advancing the pilot switch under control of the A-line, as described. If the B-telephone lift the receiver, 52nd circuit is closed for current supply to the B-line, tracing the circuit through No. 9 pilot stop position instead of No. 10 pilot stop position, and charging relays 203 and 204, in turn closing 58th circuit.

The 58th circuit (charging pilot clutch through No. 9 stop position under control of B-line) extends from minus battery (Fig. 3) over right movable and front contact points of charged relay 204, wire 178, (Fig. 2) pilot points 19X14-20X14, wire 192, pilot clutch magnet 215, and to plus battery.

The pilot brushes leave their No. 9 stop position and upon reaching No. 10 stop position find 58th circuit again closed, through pilot points 21X14-22X14, instead of 19X14-20X14, so that the brushes continue their movement and stop in No. 11 stop position, where the pilot switch awaits either the lifting of the A-telephone to complete the connection or the restoration of the B-telephone to the hook, to release the connection.

If the A-telephone be lifted at this time, with the pilot brushes at rest in No. 11 stop position, 55th circuit will be completed and the brushes will move to No. 12 stop, or talking position.

If, with the brushes at rest in the No. 11 stop position, the B-telephone be restored to its hook, 59th circuit will be formed, advancing the brushes from that position.

The 59th circuit (charging pilot clutch through No. 11 stop position with both telephone hooks down) extends from minus battery (Fig. 3) over right movable and back contact points of discharged relay 204, wire 105, (Fig. 2), pilot points 23X14-24X14, wire 192, pilot clutch magnet 215, and to plus battery.

Immediately upon reaching No. 12 stop position, 57th circuit is formed from minus battery (Fig. 2), over wire 109, pilot points 25X13-12, wire 179, (Fig. 3), movable and back contact points of discharged relay 202, to wire 523, where it is joined by the multiple path from minus battery (Fig. 3) over right movable and back contact points of discharged relay 204 to wire 523 extending thence over wire 105, (Fig. 2), pilot points 25X14-26X14, wire 192, pilot clutch magnet 205, and to plus battery.

The circuits described above, namely, 58th and 59th, together with circuits previously described, provide for the release of a connection from any pilot waiting position by the B-line without the coöperation of the A-line.

With the pilot brushes at rest in the No. 10 stop position, the A-line is awaiting the response of the B-line and the B-line is being rung upon. The action following the response of the B-line has been described. If the A-line restore the receiver to the hook, either by reason of receiving the busy tone or by reason of a decision that the B-line "does not answer" or for any reason, relays 201 and 202 are discharged and 60th circuit

is formed to move the pilot brushes from the No. 10 position.

The 60th circuit (charging pilot clutch through No. 10 stop position under control of A-line) extends from minus battery (Fig. 3) over right movable and back contact points of uncharged relay 204, wire 523, back and movable contact points of discharged relay 202, wire 179, (Fig. 2) pilot points 21X12-13, wire 192, pilot clutch magnet 215 and to plus battery.

When the brushes reach No. 11 stop position, 59th circuit is closed and when the brushes reach No. 12 stop position, 57th circuit is closed, passing the brushes to No. 13 stop position, which is a releasing position.

(6) Restoration.

The pilot brushes, upon reaching No. 13 stop position, close 61st and 62nd circuits simultaneously to charge the clutches of A-switch and B-switch for the restoration of those switches to normal. The time limit for the closing of these circuits is fixed by a predetermined angle of rotation of the A-switch and after the lapse of that time limit, the A-switch closes 63rd circuit to advance the pilot switch to its No. 14 stop position. The A-switch further determines the time of closing 66th circuit to advance the pilot to normal. Thus in the restoration of the connective division to normal, the A-switch is utilized as auxiliary to the pilot switch, it having finished all necessary functions as an A-switch.

The 61st circuit (charging B-switch clutch for restoration) extends from minus battery (Fig. 2) over wire 109, pilot points 29X13-12, wire 141, (Fig. 5), through interconnector switch as adjusted, wire 444, through closed off-normal trunk test points 237 of the B-switch, wire 514, B-clutch magnet 238, and to plus battery.

The 62nd circuit (charging A-switch clutch for restoration) extends from minus battery (Fig. 1) over A-switch points 39X2-3 in the case of calling line No. 714, wire 145, (Fig. 2), pilot points 28X10-11, wire 186, (Fig. 1), A-clutch magnet 216, and to plus battery. This circuit is broken as soon as the A-switch brushes in 3rd quadrant of the cylinder leave the 44th points; that is, as soon as all directory-number notches of the A-clutch disk have passed the clutch dog. The A-switch brushes stop thirty points off normal, on the 31st, 42nd and 20th sets of cylinder points.

The 63rd circuit (charging pilot clutch through No. 13 stop position under control of A-switch) extends from minus battery (Fig. 1) over A-cylinder points 42X2-31X2, wire 110, (Fig. 2) pilot points 28X14-29X14, wire 192, pilot clutch magnet 215, and to plus battery.

The time interval between the closing of 62nd and 63rd circuits is sufficient to permit the secondary connector clutch to move its disk until the last notch has passed the 5 clutch dog, after which time the cylinder brushes can stop only in normal position. Upon the closing of 63rd circuit, the pilot brushes move, break 61st and 63rd circuits and stop in No. 14 pilot stop position, closing 10 64th and 65th circuits for restoring the interconnector and the signal controller, in case the latter switch is off-normal at this time by reason of a selected line tested busy in pilot position No. 6. The pilot also closes 15 67th circuit to restore the A-switch from 31st set of points, and the A-switch in turn upon reaching normal closes 66th circuit to restore the pilot to normal.

The 64th circuit (charging interconnector 20 clutch for restoration) extends from minus battery (Fig. 2) over wire 109, pilot points 31X13-12, wire 143, (Fig. 5), interconnector clutch magnet 219 and to plus battery.

The 65th circuit (charging signal controller clutch magnet for restoration if off normal) extends from minus battery (Fig. 2) over wire 109, pilot points 30X13-12, wire 133 (Fig. 4), signal controller points 43X11-12, wire 506, signal controller clutch 30 magnet 213, and to plus battery.

The 67th circuit (charging A-switch clutch for restoration from 31st set of points) extends from minus battery (Fig. 1) over A-switch points 42X2-31X2, wire 110, 35 (Fig. 2), pilot points 30X10-11, wire 186, (Fig. 1), A-clutch magnet 216, and to plus battery. This circuit is broken as soon as the A-switch brushes move.

The 66th circuit (charging pilot clutch 40 through No. 14 stop position for restoration to normal) extends from minus battery (Fig. 1) over cylinder points 1X2-12X2, wire 111, (Fig. 2) pilot points 30X14, 31X14, wire 192, pilot clutch magnet 215, 45 and to plus battery.

This completes the restoration to normal of all the switches used in the connection, the register of each cylinder being restored by the return of the cylinder to normal and 50 the ringing register being restored by the return of the pilot brushes to normal.

(7) Lamp signals.

Associated with the switches of each connective division is a system of lamp circuits 55 controlling three lamps 261, 262, and 263, having caps respectively red, white and green. These lamps, by their glowing and the order of their appearance and disappearance afford an index to the condition of the division (paragraph K).

The red lamp 261 and the white lamp 262, are connected directly to the contact bank 60 of the pilot switch and, by their respective illuminations, indicate the position in which

the pilot switch is at rest from time to time. The green lamp is connected to contact points of a timing device or slow relay and the glowing of the green lamp 263 indicates that the pilot switch has remained in some 70 one of its positions or groups of positions throughout a period of time which may be designated as a time limit. This time limit is not the same for all of the positions of the pilot switch. 75

The timing device, (paragraph M.), comprises a ratchet disk 281 and two magnets with pawls, magnet 282 for driving the disk 281 against its spring 283, and magnet 284 for releasing the disk for restoration. The 80 ratchet disk 281 carries a stud 285 which operates after a sufficient number of driving impulses, first, to close a first pair of contact springs 286-287 to illuminate the green lamp 263, and upon a subsequent driving 85 impulse, to close a second pair of contact springs 288-289 connected to the pilot clutch magnet 215 and to minus battery.

The length of time required after starting from its normal position and before 90 closing its alarm and clutch contact points (paragraph N) is measured by the same number of impulses or ratchet teeth at all times (an adjustment being provided initially to determine the number of impulses required) and the total time period is regulated by the frequency of the driving impulses. Commutators traveling at different speeds provide impulses of different frequencies, providing variant time limits from 100 the same timing device. 95

Assuming that the ratchet disk 281 is adjusted to close its alarm points after the 4th impulse, impulses may be furnished at the rate of one in each 3 seconds during the 105 process of setting up a connection, and if the setting up of the connection is not completed within 12 seconds, the alarm contacts 286-287 will be closed and the green lamp 263 will glow for 3 seconds. During conversation, impulses may be furnished at the rate of one in each 6 minutes and should any conversation endure longer than 24 minutes, the alarm contacts 286-287 will be closed and the green lamp 263 will glow for 6 110 115 minutes to call the attention of the attendant.

The second pair of timer contact points 288-289 are associated with the pilot clutch and are included in 68th circuit. 120

The red-lamp circuit extends from plus battery (Fig. 3) through the red lamp 261, wire 159, (Fig. 2), pilot points on 7th level, wire 127, (Fig. 8), wire 420 and to minus battery. 125

The red-lamp circuit (paragraph Q) closed initially in No. 2 pilot position on points 36X7-37X7, is continued by the point-and-brush combinations, 4X7-37X7, 6X7-39X7, 8X7-41X7, 42X7-43X7, 43X7- 130

11X7, 12X7-1X7, until the main pair of brushes stop in position No. 6, the auxiliary pair at that time resting upon points 2X7 and 3X7.

The red-lamp circuit is closed again when the pilot brushes leave No. 6 stop position, over points 4X7-15X7, 6X7-17X7, 8X7-19X7, until the pilot brushes leave No. 9 stop position.

12 The red-lamp circuit is not closed in No. 10 stop position (repeated ring), in No. 12 stop position (talking), nor in No. 1 stop position (normal).

13 The red-lamp circuit is closed in No. 11 stop position over pilot points 12X7-23X7.

The red-lamp circuit is closed after leaving talking position over pilot points 16X7-15X7, 28X7-17X7, 30X7-19X7, 32X7-21X7, 33X4-34X4 and wire 139 to minus battery,

29 35X4-34X4 and wire 139, 36X7, 36X7-37X7, 38X4-37X4 and wire 139, 28X7-39X7, 30X7-41X7, 32X7-43X7, 44X7-1X7.

The white-lamp circuit extends from plus battery (Fig. 3) through the white lamp

25 262, wire 154, (Fig. 2) pilot points 22X7-21X7 when pilot brushes are in No. 10 stop position, wire 127, (Fig. 8), wire 420 and to minus battery. The circuit is repeated over pilot points 24X7-23X7 when pilot brushes are in No. 11 stop position.

35 The green-lamp circuit extends from plus battery (Fig. 3) through the green lamp 263, wire 540, contact points 287-286 of the timer, wire 447, alarm relay 259, wire 448, through lamp-and-release switch 264 and to minus battery.

40 The 68th circuit (pilot release by timer) extends from plus battery (Fig. 2) through pilot clutch magnet 215, wire 157, (Fig. 3), timer springs 288-289 when closed, wire 449, lamp-and-release switch 264 when closed and to minus battery.

45 The lamp-and-release switch (paragraph P) 264 has but two positions, in one of which it opens the green-lamp circuit and in the other of which it opens the 68th circuit, but it is unable to open both circuits at the same time. Hence the lamp-and-release switch controls both circuits to render one of them but not both of them at the same time. The lamps are unnecessary when the exchange is unattended, but at such a time the 68th circuit is desirable.

55 The switch 264 renders automatic the substitution of the one for the other.

60 When it is desired to have both the green-lamp circuit and the 68th circuit operative at the same time, the green-lamp circuit is closed by switch 264 and the 68th circuit is closed by switch 265. In this case, when the timer is on the fast drive the green lamp will glow 3 seconds and the division then will release if it has not received attention, 65 and when the timer is on the slow drive the

green lamp will glow 6 minutes and the division then will release if it has not received attention.

If it is desired to have the glowing of the green lamp accompanied by an audible signal, the alarm switch 260 may be closed. 70

The release circuit may be made to close before the alarm circuit if desired by including in 68th circuit timer points 286-287 in lieu of 288-289, and by including in the 75 green lamp circuit timer points 288-289 in lieu of 286-287.

The interpretation of the lamp signals is as follows:—

80 With a red lamp glowing alone, its connective division is actively engaged in setting up a connection or in restoring the switches after disruption of a connection.

With a white lamp glowing alone, the A-telephone is off the hook and the B-telephone 85 is being rung periodically.

With a green lamp glowing alone, the connective division has been in No. 12 stop position (talking position) for the time limit.

90 With all lamps dark, the connective division is in the talking position within the time limit, or is idle and normal.

95 With red and green lamps glowing at the same time, their pilot switch is in one of its transient stop positions and has been longer than the time limit in setting up or restoring its switches.

100 With the red and white lamps glowing at the same time (paragraph Q) the B-telephone is off the hook and the A-telephone 100 is not off the hook, indicating that the called party has answered the call and the calling party either has abandoned it or is negligent in lifting his receiver. The pilot brushes are standing in No. 11 stop position. By this special signal I am able to produce independent signals from the A-line and B-line, yet avoid the cost of a B-line lamp, combining the red off-normal lamp with the white A-line lamp as a substitute. 105

110 With all three lamps burning at the same time, the condition which holds the pilot brushes in No. 11 stop position will have endured long enough to reach the time limit. 115

115 The red lamp burns in all transient positions except No. 6 and No. 10 stops and is dark for a brief interval while the pilot brushes pass No. 6 stop position. No. 6 stop is a position immediately following the test upon the selected line. If the selected line is found idle by test, then when the pilot brushes reach No. 6 stop position, relay 204 will be uncharged, and will not be charged immediately by relay 204 but relay 204 instead through its contact points will charge the signal controller clutch over 38th circuit and the pilot brushes must rest in No. 6 stop position until the controller brushes move from 43rd set of points to their first 125 13

set of points, at which time 40th circuit will be closed to advance the pilot brushes farther. By this pause of the pilot brushes in No. 6 stop position, the interval of darkness of the red lamp will be so extended as to be decidedly noticeable.

If, however, (paragraph K) the selected line is found busy by test, then the locking relay 204 will be charged during all the time that the pilot switch is in its No. 6 stop position, and the following circuit will be closed.

The 69th circuit (red-lamp busy-test circuit killing red-lamp wink) extends from plus battery (Fig. 3) through the red lamp 261, wire 159, (Fig. 2), pilot points 13X5-14X5, wire 178, (Fig. 3), right front and movable contact points of locked relay 204 and to minus battery. Current over this path keeps the red lamp glowing at the time when it is normally dark in pilot No. 6 stop position, and produces a variation in the sequence of visual signals, by which variation in sequence, rather than by a distinct signal, an observing attendant may be advised that the selected line was found busy by test.

The normal sequence of lamp operations is red, dark, red, white, dark, red. The indications are red while setting the selective switches, dark while awaiting the signal controller movement after busy test upon an idle line, red during the first ring, and while awaiting the lifting of one of the telephone receivers, white during the periodic ring, dark during conversation, red during restoration. A short white flash is given during restoration as the auxiliary brushes pass pilot points 22X7 and 24X7. This flash is meaningless and is neglected.

Upon a call engaging a busy line, the sequence of lamp operations is red, white, red. The indications are red continuously until the No. 10 pilot stop position is reached, white while the calling subscriber has his receiver off the hook in the repeated-ring position, during which time he will hear the busy tone, and immediately red upon the restoration of the calling telephone to its hook, there being no long dark period for conversation.

Upon a "don't answer" call in which the selected line is engaged and rung but does not respond to the call, the sequence of lamp operations is red, dark, red, white, red. The indication by the dark interval between the first two red intervals is that the line was found idle. In this case some indication of the calling subscriber's action may be learned from the operation of the white lamp. If the white lamp is kept glowing for many seconds, the A-line is awaiting the response of the B-line; but if the white lamp flashes very briefly, then the A-line has abandoned the call without awaiting the response of the

B-line as would be the case of a test call in which the user of the A-telephone merely desired to test the telephone or to exhibit its operation to a visitor, or in which no connection or conversation was desired.

70

In a reverting call, the sequence of lamp operations is red, dark, red, dark, red. In a reverting call, the B-line and A-line being the same, relays 201, 202, 203 and 204, all will be charged simultaneously when a telephone is taken off the hook. For this reason the pilot brushes will not stop in the No. 10 or periodic ringing position and the white lamp will receive but a transient flash.

75

(8) Normaling.

80

The automatic normaling of an abnormal connective division is attained by two independent means which become operative to normal the division under various conditions of abnormality.

85

(First): The timer circuit (68th) will advance the pilot switch and ultimately normal the entire division in event of delayed control from the usual source of control.

90

(Second): The primary connector or A-switch by returning to normal or by stopping upon its 31st set of points also will advance the pilot switch from certain pilot positions of rest and ultimately will normal the entire division in case the primary connector should return to normal prematurely. These means are additional to restoration by subscriber's control from conditions or positions not abnormal.

100

A system of mutual circuits exists between the pilot switch and the A-switch. In pilot position No. 2 the A-switch is set off normal, and the pilot switch will advance without coöperation of the A-switch into pilot stop position No. 9. However, if the A-switch has not stopped upon a selective position, that is, with its brush 267 upon a point in the first quadrant, then it will have stopped with that brush upon point 31X2 by the time the pilot switch reaches its No. 8 stop position, and a normaling circuit (70th) will be closed to advance the A-switch to its normal position.

105

The 70th circuit (normaling A-switch from pilot No. 8 stop position) extends from minus battery (Fig. 1), cylinder points 42X2-31X2, wire 110, (Fig. 2), pilot points 17X10-11, wire 186, (Fig. 1), A-switch clutch magnet 216 and to plus battery. The A-switch brushes advance from 31st set of points and interrupt 70th circuit, the brushes then stopping in normal position.

110

The pilot brushes having advanced without the A-switch coöperation and having stopped in No. 9 pilot stop position, the pilot clutch magnet 215 is placed under control of either relay 202 or relay 204 or both. If a B-line has been selected, relay 204 may be under control of a telephone upon the

120

125

130

selected line, but relay 202 cannot be at this time under control of a telephone upon a telephone line because the A-switch brushes are at normal.

5 The control of relay 202 by any telephone circuit being impossible under the abnormal conditions assumed, its control is transferred to a purely local circuit within the connective division (71st circuit) and by the 10 action resulting, the pilot of the division is set forward to result in ultimate normaling.

The 71st circuit (advancing pilot from No. 9 stop position by normal A-switch) extends from minus battery (Fig. 3), through 15 helix of relay 202, wire 103 (Fig. 2), pilot points 20X1-19X1, wire 112 (Fig. 1), A-switch cylinder points 34X3-2, wire 158 (Fig. 2), pilot points 19X11-10, wire 188 (Fig. 3), resistance 211 and to plus battery. 20 This circuit charges relay 202 over a local circuit in lieu of a telephone line circuit, the substitution being made because of the irregular action of the A-switch.

By the energization of the relay 202 and 25 the operation of its armatures, the 50th circuit is closed, advancing the pilot brushes from No. 9 stop position as though controlled by an artificial A-line. As the pilot brushes leave No. 9 stop position, they break 30 the 71st circuit, discharging relay 202 and when they reach No. 10 pilot stop position, they close 60th circuit as though the telephone had been hung up upon the artificial line which advanced the pilot switch from 35 No. 9 stop position. In No. 11 stop position, the pilot brushes close 59th circuit and in No. 12 pilot stop position they close 57th circuit, advancing them further to No. 13 stop position which is an automatic release 40 position.

In No. 13 stop position the pilot brushes start the B-switch for restoration over 61st circuit and start the A-switch upon a second revolution by charging its clutch over 72nd circuit.

45 The 72nd circuit (charging A-switch clutch with A-switch normal and pilot in stop No. 13) extends from minus battery (Fig. 1), cylinder points 1X2-12X2, wire 111 (Fig. 2), pilot points 28X13-12, wire 186 (Fig. 1), A-switch clutch magnet 216 and to plus battery.

The A-switch clutch is held charged 55 through the first quadrant by 62nd circuit and the brushes reach the 31st set of points closing the 63rd circuit after which 64th, 65th, 66th and 67th circuits are closed, as described for usual release and restoration.

When the pilot switch is in normal position, the 73rd, 74th, and 75th circuits are 60 closed within the pilot switch for restoring the A-switch from any stop position other than normal and for restoring the signal controller from its sole off-normal stop position upon its 43rd set of points.

The 73rd circuit (charging A-switch clutch through selective position and normal pilot) extends from minus battery (Fig. 1) points in second and third levels of 4th quadrant of A-switch, wire 145 (Fig. 2), 70 pilot points 1X10-11, wire 186 (Fig. 1), clutch 216 of primary connector and to plus battery.

The 74th circuit (charging A-switch clutch through sub-normal position and normal pilot) extends from minus battery (Fig. 1) cylinder points 42X2-31X2, wire 110, (Fig. 2) pilot points 2X10-11, wire 186 (Fig. 1), primary connector clutch magnet 216 and to plus battery. 75

The 75th circuit (charging signal transmitter clutch through sub-normal position and normal pilot) extends from minus battery (Fig. 2), pilot points 2X13-12, wire 133 (Fig. 4), cylinder points 43X11-12, wire 506, 80 signal controller clutch magnet 213 and to plus battery. 85

The normalizing circuit of the timer (68th circuit) has the task of normalizing the entire division when a predetermined time limit 90 has expired.

Where a timer such as I have described (paragraph M) is used in connection with a connective division such as I have described, a single timer may be made to serve all the 95 switches of a division by associating it with the pilot switch.

In so using the timing device, I divide the action of the pilot switch into three parts. First, the setting up of the connection, including all action up to the lifting of one of the receivers from the telephone hook; second, the period of conversation, being measured from the lifting of a receiver from a hook to the hanging up of a 100 receiver upon its hook; third, the period of release and restoration of the switches of the division. The first period occupies a small fraction of a minute; the second period may have a definite limit by the 105 service agreement existing between the subscribers and the telephone company or it may have an arbitrary limit for a reasonable maximum telephone conversation, say ten, twenty or thirty minutes; the third period 110 will require but a small fraction of a minute. To give the same time limit or the same timer adjustment to all three of these periods would not meet fully the requirements of an 115 automatic telephone exchange. 120

I meet the requirements of such a connective division with a single timing device by providing a single timing device (paragraph S. D.) with two sources of driving power adapted to drive the device at different speeds. By this means I am able to drive the device rapidly for the first and third periods and slowly for the second period. 125

In connection with an impulse driven tim- 130

ing device a pilot switch and two sources of impulses of different speeds, I provide a circuit (76th) for the driving magnet of the timing device which passes through the pilot 5 switch to the fast impulse device in all stop positions of the pilot switch in which the connection is being set up, I provide a break in the driving circuit between the stop positions of the pilot switch for setting up the 10 connection and the stop positions for conversation, I provide a circuit (77th) from the driving magnet of the timer to the slow impulse device in all stop positions of the pilot switch classified as conversation stop 15 positions. I provide an interruption in the driving circuit between the pilot stop positions classified as conversation stop positions and the pilot stop positions for release of the division. I provide a circuit (76th) from 20 the driving magnet of the timer to the source of fast impulse through pilot stop positions for release of the division. I provide an interruption for the driving circuit between the last stop position for release and the normal 25 stop position of the pilot switch. I also leave the driving circuit open when the pilot switch is normal. In each of the three interruptions of the driving circuit provided as above described, I provide a release circuit 30 (78th) through the pilot switch while in motion and operating to release and restore the timing device.

The second pair of timer points also restore the timer itself, since by them the pilot 35 is driven until the pilot releases the timer to open the second pair of points.

It is obvious that the release may be mechanical between the moving parts of the pilot switch and the timer if so desired.

40 The 76th circuit (timer fast drive) extends from minus battery (Fig. 3) through commutator 277, wire 167, (Fig. 2) pilot points 3X8-4X8, wire 152 (Fig. 3), timer driving magnet 282 and to plus battery. 45 This circuit is closed over successive pilot points until the pilot brushes leave No. 9 stop position. It is closed again in No. 13 and No. 14 stop positions.

The 77th circuit (timer slow drive) 50 extends from minus battery (Fig. 3) through commutator 269, revolving slowly, over wire 125 (Fig. 2) pilot points 22X8-21X8, wire 152 (Fig. 3) timer drive magnet 282 and to plus battery. This circuit is closed over successive pilot points in stop positions 10, 11 and 12. In all of these positions at least one telephone receiver must be off the hook to prevent the pilot switch from going to an automatic release position.

55 The 78th circuit (timer release by pilot) 60 extends from minus battery (Fig. 2) pilot points 20X3-21X3 which are closed by brushes in motion between No. 9 and No. 10 stop position but which are not closed in

either stop position, wire 151 (Fig. 3) timer 65 release magnet 284 and to plus battery.

This circuit is closed as above after the setting up of the connection and upon the removal of either telephone receiver from the hook, at which time the timer is released and 70 restored to start from its normal position for its long period upon the slow drive. After conversation, the timer is restored by a similar circuit over pilot points 27X3- 75 28X3; and after restoration of the switches, 80 as the pilot switch leaves No. 14 stop position, the timer is restored again through 78th circuit over points 20X3-21X3, those points being closed in this instance by the auxiliary brushes.

The use of the timer upon a connective division insures the proper operation within reasonable limits both of the connective division and of the telephone users served by the division at any time. I extend this principle 85 in my improved automatic telephone exchange (paragraph S. E.) by associating a similar timer with the division starter. The timer associated with the division starter insures the proper operation within reasonable limits, both of the division starter itself and of the division being started.

The timer of the division starter is shown 90 in Fig. 9. It has three circuits, 79th 95 80th and 81st.

The 79th circuit (drive circuit for starter timer) extends from minus battery (Fig. 3) through commutator 276, wire 446, 440, (Fig. 9), starter point 3X8 and through the starter brushes to point 3X7, while the 100 starter brushes are in their sub-normal stop position to close 4th circuit, thence over wire 461 to drive magnet 220 of the starter timer.

The 80th circuit (release circuit for starter timer) extends from minus battery (Fig. 9) 105 wire 418, starter cylinder points 4X7-8, wire 460, timer release magnet 221 and to plus battery. This circuit is closed transiently while the starter brushes are in motion from sub-normal position of starting the division 110 to the next normal position of waiting for a subsequent call. At this time, the starter timer is restored to its normal position of idleness.

The 81st circuit (release of starter by 115 timer) extends from minus battery upon contact points 222 of starter timer and when the timer has closed its contacts, it extends to contact point 223 and over wires 462 and 501, to and through clutch magnet 218 and 120 wires 503 and 424 and to plus battery.

The starter timer may be adjusted to a very short period of time, say 5 or 10 seconds, and if a division is not operated to the No. 3 pilot stop position within that 125 time limit, then the timer will set the starter brushes forward, which in turn will restore the timer and the time limit will be repeated.

as the starter comes to rest in sub-normal position to start the next idle switching division.

An "out of service" condition of the division starter (paragraph S. F.) is desirable when all divisions are busy, that the starter may not rotate needlessly. To prevent this needless rotation, I provide an "out of service" stop notch in the starter clutch disk which stops the brushes upon the No. 41 set of points. The only circuit involved is the 82nd circuit which is closed by any normal pilot switch of the section and which, when closed, passes the starter 15 brushes from the No. 41 set of points.

The 82nd circuit (division starter "out of service" circuit) extends from minus battery (Fig. 2) wire 109 pilot points 1X13-12 of any pilot switch of the section, wire 126, 20 (Fig. 9) starter cylinder points 41X3-4, wire 501, cylinder magnet 218, wires 503 and 424 and to plus battery.

This circuit is normally closed and renders the starter operative. When the 82nd 25 circuit is opened, it renders the division starter inoperative or "out of service."

(9) *Special services.*

Rotational selection.

30 The circuits of the rotational selection system (paragraph S. G.) are shown in Fig. 12 in which are shown parts of several connective divisions. The cylinder brush 224-1 is the brush bearing the same label in Fig. 5 upon cylinder point 34X10. The wire 444 is the wire 444 of Figs. 5 and 6. As this wire is intermediate between 444-1 and 444-3 it might properly bear a label 444-2, being the wire 444 of the 2nd secondary 40 connector.

The cylinder brush 224-1 is a part of the interconnector of the 1st connective division and represents the complete connective division as shown in Figs. 1, 2, 4, 5 and parts 45 of Fig. 3. The cylinder brush 224-2 is a similar brush in the 2nd connective division and represents a complete similar division. The dotted lines extending to the left above the brush 224-2 indicate the existence of 50 still other similar connective divisions, related to the 1st and 2nd divisions as those divisions are to each other, namely by embracing terminals of the multiplied test wires 444-1 to 444-7 inclusive. In connection with the brush 224-1 is shown a row 55 of eleven cylinder contact points, being those cylinder contact points in 11th level of 4th quadrant of Fig. 5, points 34X11 to 44X11 inclusive, and connected to the test 60 wires of the successive trunks of a group of trunks extending to a group of secondary connectors. Similar points are shown for the brush 224-2 and similar points exist in analogous connective divisions.

Of the trunks extending from the inter- 60 connectors to the secondary connectors, only the test wires 444 and similar are shown in Fig. 12, only those wires being involved directly in the rotational test circuits.

The secondary connector of Fig. 6 is the 70 2nd of the group and its parts appear in Fig. 12 as follows: cylinder magnet 238, off-normal switch 237, connecting conductor 514, trunk conductor 444 for test and clutch control. These parts which are involved in the rotational test system, as applied to the specific machine telephone apparatus disclosed in this application, serve to indicate the complete secondary connector of Fig. 6. They are duplicated at 80 238-1, etc., to represent the complete 1st secondary connector of the set and they are further duplicated at 238-3, 238-4 and 238-5 to indicate still other complete secondary 85 connectors.

In addition, and specifically for the purpose of the rotational test, three relays 206-1, 206-2, 206-3 are provided for the 1st, 2nd and 3rd secondary connectors respectively.

The relays 206-1, 206-2 have each two armatures of which the right armature has a back contact spring which follows the armature substantially until the front contact spring of that armature is engaged, thus affording energization for the helix through the armature and back contact for sufficient length of time to enable the relay to lock electromagnetically over a circuit through its armature and front contact. The relay 206-3 is a simple relay breaking its armature circuit when its core is charged. The relays 206-1 and 206-2 are of high resistance and adapted to carry current from the main battery 200 continuously or for long periods. The specific operation of these apparatus parts is that the act which charges the clutch magnet 238-1 shall charge also the relay 206-1 (83rd circuit) which relay will lock (84th circuit) and produce and maintain a false busy test or guard circuit (85th circuit) upon the test conductor 444-1 associated with that secondary connector, so that the next succeeding call will pass 90 that secondary connector as being engaged whether the secondary connector actually is engaged or not. While the secondary connector is engaged in fact, the 23-2nd circuit or fact-busy circuit will exist in addition to the 85th or false-busy circuit. After the removal of the fact-busy by reason of the restoration of the secondary connector to normal, the false busy will continue by reason of the locked relay 206-1.

Upon the promotion of the next call into this set of secondary connectors, whether from the 1st division having brush 224-1, from the 2nd division having brush 224-2,

or from any other division, the wire 444-1 will give a busy test to the 23rd circuit and the interconnector will search further and take the 2nd secondary connector, having tested over wire 444, and having found that wire open both at the off-normal switch 237 and at the left armature of the relay 206-2. Upon operating the decimal register of the secondary connector, the switch 237 closes and upon operating the clutch 238 (34th circuit) the relay 206-2 is charged (83rd circuit) and locks (84th circuit) producing a false guard (85th circuit) upon the guard wire 444. This false guard continues regardless of the continuance or discontinuance of the fact guard upon the wire.

Upon the receipt of the next succeeding call into the group of secondary connectors, the searching interconnector will find busy by test both the wire 444-1 and the wire 444 and will search further for a wire idle by test, engaging and accepting the wire 444-3. Upon the operation of the register, the switch 237-3 will be closed and upon the operation of the clutch 328-3 over the wire 444-3, the control relay 206-3 will be charged over 86th circuit. By the charging of the relay 206-3, 84th circuit will be broken and relays 206-2 and 206-1 will be released, removing the false busy from the test conductors 444 and 444-1.

The conductor 444-2 never carries a false test. It is the control conductor of the group and the last conductor of the rotational group.

The object of dividing the total trunks into two groups (paragraph S. H.) of which the 1st group is rotational and the 2nd group ordinal, is found when a plurality of calls are received very closely following each other. If all trunks are rotational and all but the control trunk are busy by false busy and two calls are received, the second call may have passed all trunks idle in fact before the first call will have removed the false busy from those trunks. Thus, the second call would be defeated and would not select a trunk although trunks were idle in fact at the time. With the two groups, rotational and ordinal, the ordinal group will care for all calls passing the rotational group in busy hours, while the rotational group will effectually provide for rotational selection upon any specific repeated call during the idle hours. It is particularly for the repeated call and particularly for the repeated call during the idle hours that my improved system of rotational selection is designed.

The relay 206-3 does not involve the high current carrying requirements of relay 206-2 or 206-1, and the relay 206-3 may be sufficiently sensitive to respond to the testing currents over 23-2nd circuit as well as to

currents over 34th and 61st circuits. By this adjustment, even though the 3rd secondary or control trunk may be fact busy when tested, the control relay 206-3 will be charged to relieve the false busy from the other units of the rotational group.

The 83rd circuit (charging rotational relay No. 6) follows 23rd circuit as far as wire 444, then extends further through off-normal switch 237, wire 463 (Fig. 12) right contact and movable contact points and relay 206-2, helix of relay 206-2, wire 464, interdivisional wire 465, closed points of relay 206-3 and to plus battery.

The 84th circuit (locking rotational relay No. 6) extends from minus battery (Fig. 12) over right front and movable contacts of charged relay 206-2, through helix of relay 206-2, wire 464, interdivisional wire 465, closed points of relay 206-3 and to plus battery.

The 85th circuit (false guard for rotational test) extends over 23rd circuit as far as wire 444, thence (Fig. 12) over wire 466 through left closed points of charged relay 206-2, wire 467, wire 463, wire 514, helix of clutch magnet 238 and to plus battery.

The 86th circuit (charging rotational control relay) extends over 23rd, 34th or 61st circuit as far as wire 444-3 thence through closed off-normal switch 237-3, wire 468, helix of relay 206-3 and to plus battery.

Service meter.

The meter circuit (54th circuit) is controlled over pilot points 23X10-11 and 24X10-11 in co-operation with the left armature of relay 203. The pilot points are closed by the two pairs of brushes bridged vertically while the pilot switch is in its No. 11 stop position.

It will be noted that the pilot switch seldom stops upon this position since it is a stop position used only in an irregular call where the user of the A-line telephone has neglected to lift the receiver promptly upon making his call. In the ordinary operation of the pilot switch, the A-line receiver being lifted before the B-line receiver is lifted, the pilot switch moves continuously from No. 10 stop position to No. 12 stop position; thus the 54th circuit is closed only transiently as the pilot brushes pass from the No. 10 stop, the position of repeated ring, or of A-line waiting for B-line to respond, to the No. 12 stop, the position of conversation, the circuit not being closed in either of the two positions mentioned. The circuit also is subject to control of the relay 203.

The 54th circuit (charging meter) extends from plus battery (Fig. 3) through left contact points of relay 203, if charged, wire 170 (Fig. 2) pilot points 23X11-10, wire 114 (Fig. 1) through the A-switch as adjusted,

wire 423 (Fig. 7), wire 445, helix of meter 225 and to minus battery.

The 15th circuit is not interrupted to form the 54th circuit, the 54th circuit being 5 formed as a shunt around the resistance 211 of the 15th circuit. The current of the 15th circuit is not sufficient to operate the meter 225 because of the resistance 211.

When the B-line telephone is lifted from 10 the hook, current is taken over 52nd circuit, charging relays 203 and 204. Relay 204 advances the pilot switch as described and relay 203 charged by the B-line and in co-operation with the pilot switch operates the 15 meter of the A-line over 54th circuit.

Free line service.

When it is desired to receive calls upon 20 a designated line as a B-line, without causing the actuation of a meter upon any calling or A-line to such a connection, a circuit is used (87th circuit) by which the relay 204 is charged and the relay 203 remains uncharged for an interval sufficient to advance 25 the pilot brushes from stop position No. 10 to stop position No. 12. This being effected, the relay 204 advances the pilot switch but the relay 203 does not coöperate with the pilot switch to close the 54th circuit. After 30 the pilot switch has attained its No. 12 stop position for conversation, the relay 203 may be charged by 52nd circuit.

The charging of the relay 204 without 35 charging the relay 203, is effected by applying upon the B-line a source of current, from the plus terminal of the main battery or equivalent, from which source current will flow through relay 204 to minus battery. This source may be a contact applied either 40 transiently or permanently, and applied either to the line conductor directly or to the sub-station telephone equipment and thence to the line conductor. In Fig. 13, the free-service source of current is applied to the 45 line conductor. In Fig. 14 it is shown as applied through a jack contact upon a manual switchboard. In Fig. 15 it is shown as applied through the sub-station telephone.

The 87th circuit (free-line circuit to avoid 50 operating meter) extends from plus battery (Fig. 13) through an inductance 226 to conductor 422 (the relay 14' being charged over 55 15th circuit at this time) from which point the circuit may be traced (Fig. 7) to the secondary connector (Fig. 6) where it joins 52nd circuit and continues through B-switch as adjusted, wire 442 (Fig. 5) through interconnector switch as adjusted, wire 144, (Fig. 2) pilot points 21X4-22X4, wire 153 (Fig. 4) signal controller points 1X5-6, wire 60 437 (Fig. 3) left points of discharged relay 205, wire 518, helix of relay 204 and to minus battery. This charges relay 204 without charging relay 203.

Assuming that line 714 extends to a manual switchboard, a variation of the 87th circuit may be traced from plus battery (Fig. 14) through closed contact of idle manual switchboard jack 227 over wire 422 and to Fig. 7, the cut-off relay 14' of Fig. 7 being 70 charged by 15th circuit at this time. From this point, the circuit may be traced as for 87th circuit traced above.

The free meter circuit of Fig. 13 is possible where the subscriber's line is long or 75 where a source of current is not available at his telephone. Its disadvantage is that the inductance leg 226 remains upon the talking conductor during conversation.

Where a source of current is available at 80 the telephone another variation of the 87th circuit may be traced from plus battery (Fig. 15) through added spring 228, of the hook switch 246 (see Fig. 10) and through 85 closed connection with depressed long spring of hook switch 246 prior to the answering 90 of the telephone user, thence over wire 422 to Fig. 7 (the cut-off relay 14' being charged over 15th circuit at this time) and thence as before over 87th circuit as traced above. 90

In each of these variations, the auxiliary 95 source of current is removed from the line when the call is answered. When a plug is inserted in jack 227, the 52nd circuit will be formed through the operator's switching 100 equipment and will charge the relay 203. When the receiver is lifted in Fig. 15, the auxiliary source of current will be removed from the wire 422 and 52nd circuit will be formed. 100

Supra-busy system.

To enable the toll operator to seize a busy line, disregarding its guard (paragraph SP), a circuit (88th) exists from the signal 105 transmitter controller clutch to the toll board whenever the busy tone is returned over a toll trunk. The means for effecting this is to use as toll trunks all trunks having the units figure "2," thereby appropriating 110 a definite position of the primary connector or A-switch cylinder brushes exclusively for toll trunks manual-to-automatic; and then wiring a circuit through this appropriated A-switch cylinder position and through the 115 signal controller sub-normal or 43rd set of points to the signal controller clutch. Over this circuit the signal controller may be advanced to normal.

The 88th circuit (supra-busy) extends 120 from minus battery upon the manual switchboard, through manual key 229, (Fig. 1), wire 469, to cylinder point 4X2 on all A-switches of the section upon which the toll-to-automatic trunks terminate. When the 125 A-switch is in that predetermined selective position which it assumes in response to a call initiated upon a toll-to-automatic trunk,

then the brush 267 will rest upon the point 4X2 and the connected brush 268 will rest upon the point 15X2. By these brushes thus adjusted by a call over any manual-to-automatic trunk, 88th circuit will be continued from wire 469, through A-switch points 4X2-15X2, wire 117, (Fig. 2), pilot points 22X12-13, wire 133, (Fig. 4), signal controller points 43X11-12, wire 506, controller clutch magnet 213 and to plus battery.

The busy tone being heard by the toll operator, the manual key 229 may be closed, thus closing the 88th circuit and advancing the signal controller to normal, removing the manual-to-automatic trunk conductors from the source of tone current and connecting them to the conductors of the selected and busy line.

20

Party-line telephone.

Fig. 16 shows the circuits of the party-line telephone (paragraph SQ). A difference is found in the wire 470 and its accompanying pin 290 with the incidental additional tooth in the ratchet. The disk 239 has its notch cut of sufficient width to permit the dog of 249 to enter the notch in two positions of the arm 242, namely, when the arm 242 is upon pin 290 or upon pin 243. When the arm is in any position other than upon pin 290 or 243, the circuit of magnet 248 is closed from ground through off-normal switch 247 to line conductor 422. When the arm 242 is upon the point 290, the switch 247 is open and the magnet 248 is connected instead from ground through conductor 470, pin 290, arm 242 and thence to line conductor 421. By this means, the magnet 248 is transferred from line 422 to line 421 while code ringing currents are sent over line 422.

Referring to Fig. 17, an interference device is disclosed (paragraph S. R.) in connection with the party-line telephone whose circuits are shown in Fig. 16. The telephone system herein shown and described as a whole may be operated without this interference device but the convenience of the system for telephone users is increased by the interference feature.

The shaft 280 carries sleeved upon it the spur gear 286. The spur gear 286 carries the pin 283 and the ratchet carries the pin 281. The two pins 281 and 283 are connected by the spiral spring 282. Thus the wheel 286 may be turned independently of the ratchet and may be operated to increase the spring tension upon the ratchet. The spur gear 287 is carried upon the crank shaft 288 and meshes the spur gear 286. The spur gear 287 carries rigidly attached to it the cam 289, the cam 291, and the pin 292. It is restrained by the pawl 293 against the action of the spring 282. The pawl 293 when lifted

by the cam 291 closes the electrical switch 294. The slide bar 295 when lifted by the pin 292 acts through pin 284 to lift and operate the armature of the magnet 248 and permits thus a step of the ratchet, the preliminary mechanical step hereinbefore referred to in the initiation of a call. The pin 292 engages the inclined cam face of the slide bar 295 just prior to the completion of one crank revolution, thus effecting the first step of the ratchet as the final act of turning the handle to initiate a call.

The cam 289 receives the tooth 285 of the cam arm of 249 when the dog of the arm 249 is out of the notch of the disk 239. When the dog of 249 is in the notch of 239, the tooth 285 is withdrawn from the path of the tooth of cam 289. Thus, if the disk 239 is normal, the armed member 249, by withdrawal of its tooth 285, unlocks the spur gear 287.

The brush 242 being normal, and spur gear 287 being unlocked, the crank may be turned one complete revolution, but no more, since when the revolution is nearly completed the pin 292 operates the slide bar 295, which, through the pin 284, operates the armature 301 and permits a step of the ratchet, which moves the disk 239, which in turn moves armed member 249 and moves tooth 285 into the path of the tooth of cam 289, thus stopping the spur gear 287 at the end of one complete revolution. The pawl 293 prevents return movement of the spur gear 287. The sending of the call follows as described in the early portions of this specification.

My improvement comprises the addition of the contacts or electrical switch 294 upon pawl 293, cam 291 upon the spur gear 287, the magnet 296 and its armature 297 which carries the interference tooth 298. The cam 291 is attached to the side of the spur gear 287 and does not interfere with the meshing of gears 286 and 287. The pawl 293 is of wide tooth and overhangs the side of the spur gear 287 so that it is engaged by the cam 291 and lifted from the spur gear teeth transiently by that cam.

The operation of my interference device is as follows: Upon beginning to turn the crank 299 and thereby turning the spur gears 287 and 286, the cam 291 raises the pawl 293 and closes the switch 294. If this results in the energization of the magnet 296, then that magnet will attract its armature 297 and draw its interference tooth 298 into the spur gear teeth, stopping the further progress of the call. Upon the release of the crank handle by the telephone user, the spring 282 will return the spur gears to normal position, since the pawl 293 is ineffective because of the cam 291. By this return, the circuit of magnet 296 is opened.

If, however, at the time of turning the crank 299 the magnet 296 is not charged, the call may progress in the usual manner.

To effect the proper operation of the magnet 296 at the proper time and at no other times, I connect the two sides of the line 422 and 421 together through the contacts of the cut-off relay 14' at the central office when the line is not in use. I then connect 10 the two conductors 491 and 492 to the two line conductors 421 and 422 respectively. When the line is idle, the two line conductors are at the same potential, being connected to the same terminal of the main battery 200, and no current flows through 296 when 294 is closed. When the line is in use, the two sides of the line are of different potentials since they are connected to the two terminals of the main battery through 15 relays 201 and 202 if the line is calling and relays 203 and 204 if the line is called; then when the switch 294 is closed, current will flow through the magnet 296, interrupting the further progress of the crank 299 as described.

I have described my invention as applying to a specific type of automatic telephone exchange and I have described specific applications of the principles of my invention 30 when used in connection with the specific exchange. I do not desire to be misinterpreted in view of such limited description, since my invention is not limited to the specific forms and applications here shown, 35 and many modifications may be made in the apparatus and details of application to an exchange without departing from the spirit or scope of my invention.

Having thus described my invention, what 40 I claim as new, and desire to secure by United States Letters Patent, is:

1. In an automatic telephone system, a pilot switch having a ringing stop position and a talking stop position and having contact 45 points engaged by brushes intermediate of said two positions; a telephone line; a meter associated with said line; and a circuit for operating said meter and passing through said contact point.

2. In an automatic telephone system, a pilot switch having a ringing stop position and a talking stop position and having contact points engaged by brushes intermediate of said two positions; two telephone 55 lines connected through said pilot switch; a meter associated with each of said lines; and a circuit under control of one of said lines for operating the meter of the other line and passing through said contact points.

3. In an automatic telephone system, a station adapted to originate a call; a meter associated with said station; a switching device responsive to said call and normally operating said meter upon completion of a

call; stations at which said call may terminate and means for controlling said switching device to defeat the operation of said meter; and other stations at which said call may terminate.

4. In an automatic telephone system, a 70 station adapted to originate a call; a meter associated with said station; a switching device responsive to said call and normally operating said meter upon completion of said call; stations at which said call may 75 terminate; a source of current at some of said stations; and means defeating registration of the call when a source of current at the terminating station is encountered.

5. In an automatic telephone system, lines; 80 a meter associated with each; connective devices for connecting any two of said lines and having a predetermined position for conversation between the two said lines; a circuit in and through a connective device 85 and the B-line of a connected pair of lines for placing said connective device in condition for conversation and for operating the meter of the A-line of the connected pair; and an additional circuit upon some 90 of said lines for attaining the condition of conversation without operating the meter.

6. In an automatic telephone system, telephone lines; a meter associated with each; 95 means interconnecting said lines in pairs and operating the meter of one line of each pair so connected; and an auxiliary circuit in connection with some of said lines for defeating said meter operation. 100

7. In an automatic telephone system, telephone lines; a meter in connection with each of said lines; connective devices responsive to said lines and operating the meter of a calling line upon a normal successful call; 105 other lines; and an auxiliary circuit for each of said other lines and permitting the completion of a successful connection from any line without the operation of any meter.

8. In an automatic telephone system, a 110 connective device; a called line connected therewith; a calling line connected therewith; a meter associated with said calling line; a relay associated with said called line to advance said connective device to 115 talking position; a relay associated with said called line to operate said meter while said connective device is advancing to talking position; and means in connection with some of said lines for charging said first 12 relay without charging said second relay, thereby advancing said connective device to talking position without operating said meter.

9. In an automatic telephone system, tele- 1 phone lines; a meter associated with each of said lines; connective devices for connecting said lines in pairs; a connection-con-

trolling relay for the called line in each such connective device; a meter-controlling relay in each of said connective devices; a circuit through some of said lines for 5 charging both of said relays when called; and a circuit through other of said lines for charging but one of said relays when called.

Signed by me at Toronto, county of York,

Province of Ontario, Canada, in the presence of two witnesses.

DAVID S. HULFISH.
